UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed March 20, 1919. Serial No. 283,693.

To all whom it may concern:

Be it known that I, ERASTUS E. WINKLEY, a citizen of the United States, residing at Lynn, in the county of Essex and State of Massachusetts, have invented certain new and useful Improvements in Heel-Building Machines; and I do hereby declare the following to be a full, clear, and exact description of the invention, such as will enable others skilled in the art to which it appertains to make and use the same.

This invention relates to heel building machines, and it has special reference to that class of machines which are adapted to build a heel, or part of a heel, from a series of lifts that are dinked out of sheets of leather, leatherboard or analogous material.

One of the general objects of the invention is to provide a machine of the above indicated character which shall be relatively compact, durable and inexpensive in construction; rapid, effective and reliable in operation; and which shall uniformly produce heels of a higher quality than has heretofore been possible.

Another object of the invention is to provide a machine of this general class for building pasted heels, which shall be so constructed and arranged as to permit of the successful use of a quick drying paste, with no liability of its setting or losing its adhesive property before the lifts are assembled. The utilization of such a paste is extremely advantageous in the art, as it contributes towards economical and expeditious manufacture and towards an improved product, inasmuch as it spreads easily and uniformly and sets rapidly so that the heel may be compressed shortly without danger of its being so "green" or wet as to later become checked and defective.

To this end, one feature of the invention comprises a lift assembling mechanism, embodying at one end a paste roll over which a series of lifts are fed in succession immediately prior to their assemblage into the form of a heel-pile, which assemblage takes place almost instantly after the pasting operation and before the paste loses any of its desirable qualities.

Another and important object of the invention is to provide an automatic machine of the character indicated which shall be adapted to build pasted heels, having their

respective outer ends entirely free of paste, and more particularly to provide a machine so constructed and arranged as to produce a base-lift and bring it into assembling position in perfectly dry condition, and to subsequently deliver the pasted lifts in superposed relation upon it.

The feature by means of which this result is attained resides in locating the base-lift magazine out of alinement with or in a different plane than the other lift magazines, and producing and feeding the base-lift and the other component lifts in different paths into the assembling position, the other lifts being pasted during their feeding movement and the base-lift traversing an entirely independent path which is free of paste so that it is maintained in dry condition.

Another object of the invention is to produce an expeditious automatic lift assembling mechanism of minimum length, while being capable of adjustment to build either men's heels of large sized lifts or women's heels of a relatively large number of smaller sized lifts.

With this end in view, a feature of the invention resides in the use of a movable conveyer having an uninterrupted plane upper surface upon which a series of lifts are deposited in a row from a series of lift magazines that are disposed adjacent said conveyer. The magazines comprise a plurality of spaced partitions that are adjustable in position longitudinally of the machine upon suitable supports in order to accommodate between adjacent partitions any desired sizes of lifts. With this construction, the magazine partitions may be spaced relatively far apart to accommodate the large lifts of men's heels or relatively near together for holding smaller lifts for women's heels, and, in either case, may be grouped together into a minimum length of space and located as far as possible towards the end of the machine to which the lifts are fed by the conveyer and assembled in the form of a heel-pile.

Such an arrangement and grouping of magazines is rendered possible by the use of a conveyer having an uninterrupted or plane surface upon which the lifts produced from the magazines are deposited, since there are no predetermined and definite positions for the magazines in order that the lifts produced therefrom shall

occupy certain relatively fixed positions upon the conveyer, as would be the case if the conveyer were provided with definitely spaced cross pieces or fingers. Moreover, although not necessarily so, the conveyer is preferably operated continuously, thereby avoiding the use of an expensive clutch and control mechanism therefor, and economizing time otherwise required to start and stop the conveyer. Furthermore, by compactly grouping the requisite magazines near the end of the machine at which the lifts are assembled, the lifts deposited upon the conveyer are fed through shorter distances and, therefore, assembled more rapidly.

Another object of the invention is to make provision for building wedge heels by the incorporation of wedge lifts at any desired place or places in the heel.

To the accomplishment of this object, wedge lift magazines which are also adjustable longitudinally of the machine are provided, and these magazines are of the rotary type, such as set forth and claimed in Letters Patent of the United States No. 1,352,746 granted September 14, 1920 to Fred V. Hart, and are disposed behind the row of main magazines in order to economize space. It is thus necessary only to provide sufficient spaces between the magazines of the front row to permit the wedge lifts to be advanced to the conveyer instead of relatively large spaces to accommodate the more bulky construction of the rotary magazines, in the event that they were located in alinement with the other magazines.

A further object of the invention is to provide a heel building machine comprising two main component mechanisms, one for building loosely assembled heels and the other for alining, pressing and nailing the heels so built; and also to make provisions whereby said mechanisms may be operated independently or together as a single unitary machine, one mechanism being under the control of the other.

To this end, a feature of the invention resides in the employment of a heel building or lift-assembling mechanism and an alining, pressing and nailing mechanism which are normally so correlated through the agency of interconnecting control mechanism that the operation of the lift-assembling mechanism is initiated automatically by the alining, pressing and nailing mechanism at a predetermined point in its cycle of operations, thus causing the component mechanisms to operate in definite time relation as a single machine. Independent operation of these mechanisms may be obtained if desired by suitably interrupting the control connection between them.

These and other objects of the invention and features by means of which they are

attained will become apparent from the following description of the preferred embodiment of the invention illustrated in the accompanying drawings.

Although the invention is illustrated and will be described as embodying a more or less specific construction, arrangement and location of parts, and mode of operation, it should be understood that the invention is not so restricted, and that many of the advantages and benefits of the invention may be derived from a machine which varies materially from that set forth. The preferred embodiment herein shown and described, therefore, is merely illustrative of the invention and, as many modifications may be made therein without departing from the spirit and scope of the invention, only such limitations should be imposed as are indicated in the appended claims.

The invention may be best understood by reference to the accompanying drawings in which:—

Figure 1 is a view in front elevation of a machine constructed in accordance with the invention; Fig. 2 is a plan view of the machine; Fig. 3 is a view in right end elevation of the lift-assembling mechanism, a portion thereof, being broken away for the sake of clearness; Fig. 4 is a left end elevation thereof; Fig. 5 is a view, partially in end elevation and partially in section, taken on the section line 5—5 of Fig. 1; Fig. 6 is a view similar to Fig. 5 and taken on the section line 6—6 of Fig. 1; Fig. 7 is an enlarged sectional view of the clutch for controlling the operation of the lift-assembling mechanism; Fig. 8 is a view in perspective of a wedge cam member which constitutes a part of the clutch; Fig. 9 is an enlarged sectional view showing the mode of mounting the base-lift magazine upon the transverse conveyer supporting frame shown in Fig. 4; Fig. 10 is a view in perspective of a portion of the table of the lift-assembling mechanism and showing the construction of the main lift magazines and the mode of producing lifts therefrom and depositing them on the main feeding conveyor; Fig. 11 is a perspective view of a portion of said table and the actuating mechanism for the pusher beam which removes a series of lifts from the lower ends of the magazines; Fig. 12 is a detail view in section of the construction for adjustably mounting one of the lift arresting fingers; Fig. 13 is an enlarged plan view of one of the rotatable wedge lift magazines and the pusher for producing lifts therefrom; Fig. 14 is an enlarged plan view, partially in section, of the apparatus for rotating the wedge lift magazine; Fig. 15 is a phantom perspective view of one of the wedge lift magazines; Fig. 16 is an enlarged view, partially in front elevation and partially in section, of a portion of one end of

- the lift-assembling mechanism, showing particularly the arrangement of the paste pot and feed wheels, and the manner of delivering the lifts into the receiving device; Fig. 17 is an enlarged view in rear elevation of the driving mechanism for operating the feed wheels; Fig. 18 is a view in perspective of one of the feed wheel driving shafts; Fig. 19 is a view, partially in section and partially in side elevation, of the removable paste pot and paste roll, the section being taken on the section line 19—19 of Fig. 20; Fig. 20 is a plan view of the paste pot and paste roll; Fig. 21 is a view, 10 partially in front elevation and partially in section, on the section line 21—21 of Fig. 19; Fig. 22 is a diagrammatical plan view showing the relative arrangement of the feed wheels; Fig. 23 is a view in right end 20 elevation of the transverse conveyer upon which the lifts are received, and showing particularly the heel rotating mechanism for turning the loosely assembled heel through a quarter turn; Fig. 24 is a plan view of 25 the apparatus shown in Fig. 23, showing the relative positions of the parts before the heel is rotated; Fig. 25 is a similar view showing the relative positions of the parts after the heel has been rotated through a 30 quarter turn; Fig. 26 is a view in right side elevation of the lift alining, pressing and nailing mechanism, showing the mechanism in its inoperative open position; Fig. 27 is 35 a phantom perspective view of one of the roll carrying members attached to the main actuating lever; Fig. 28 is a plan view of the lift alining, pressing and nailing mechanism, certain portions being broken away for the sake of clearness, and 40 the mechanism being shown in its inoperative and open position; Fig. 29 is a view in front elevation of the mechanism shown in Figs. 26 and 28, illustrating the mechanism in its closed operating position; Fig. 30 is 45 a sectional view on the line 30—30 of Fig. 29; Fig. 31 is a detail view in front elevation of the end of the nail feeding tube and nail holder; Fig. 32 is a view, partially in side elevation and partially in section, on the line 32—32 of Fig. 28 and showing the 50 parts in their clamping and nailing positions; Fig. 33 is a view similar to Fig. 32, showing certain parts of the heel receiving and holding device adjusted to act upon a 55 high woman's heel and properly position it for the nailing operation; Fig. 34 is a view, partially in front elevation and partially in section, upon the section line 34—34 of Fig. 32 of the apparatus shown in said figure; 60 Fig. 35 is a view in left side elevation of a portion of a heel receiving and holding device and the alining and clamping form, illustrating the relative positions of the various parts while alining the component lifts in loose order; Fig. 36 is a sectional detail 65 view of a portion of the automatic nail supplying mechanism; Fig. 37 is a view, partially in side elevation and partially in section, on the line 37—37 of Fig. 34 and showing particularly the mechanism for locking 70 the main actuating lever against retraction during the power actuated portion of the cycle of operations; Fig. 38 is a view in side elevation and partially in section of the alining and clamping form, showing the 75 form in its open position; Fig. 39 is an enlarged perspective view of a roll carrying member that is attached to the actuating lever; Fig. 40 is a view in front elevation of a portion of the automatic nail supplying 80 mechanism; Fig. 41 is a similar view in side elevation; Fig. 42 is a plan view of the mechanism shown in Fig. 41; and Fig. 43 is an enlarged detail view in perspective of a 85 portion of the nail supplying mechanism, showing particularly the construction of the nail holding means.
- Referring to the drawings, and particularly to Figs. 1 and 2, the heel building machine constituting the present invention, comprises, in general, a lift-assembling mechanism 50 and an alining, pressing and nailing mechanism 52, both of which are conveniently mounted in side by side relation upon a main supporting bed comprising a plurality of longitudinally extending beams 53.
- The lift-assembling mechanism 50 is semi-automatic in its operation, and is adapted to produce a row of lifts sufficient in number and of the proper graded sizes and characteristics to form a heel and to feed the row of lifts serially and in rapid succession over a pasting device after which they are immediately assembled in superposed relation at a station so positioned that the loosely assembled heel or heel-pile may be readily accessible for removal by the operator.
- The aligning, pressing and nailing mechanism 52 is mounted adjacent the assembling station of the lift-assembling mechanism 50 in order that the operator may easily remove and transfer the loosely assembled heel from said station and place it in the alining, pressing and nailing mechanism. This mechanism is semi-automatic in operation, being under the direct control of the operator and is adapted to aline the loosely assembled lifts of the heel, to subject the heel to pressure and clamp it firmly in its final form while its component lifts are permanently nailed together.
- Both the lift-assembling mechanism 50 and the alining, pressing and nailing mechanism 52 are of the single cycle type which, after completing a single cycle of operations are automatically arrested until again thrown into action under the control of the operator. Under normal operating condi-

tions, the two mechanisms are correlated and dependent, and are interconnected in such manner that they are controlled as a unit and cooperate as a single unitary machine, the operation of the lift-assembling mechanism being governed by that of the manually controlled semi-automatic alining, pressing and nailing mechanism. If desired, the two mechanisms may be controlled independently.

In the interests of clearness and ready understanding, the description of the invention will first be directed to the lift-assembling mechanism 50 and then to the alining, pressing and nailing mechanism 52, after which the interconnecting control apparatus by means of which the coaction of these two mechanisms is secured, will be set forth.

Having particular reference to Figs. 1 and 2, the lift-assembling mechanism 50 comprises, in general, a supporting frame upon which the component parts of the mechanism are mounted; a plurality of main lift magazines 54 for containing stacks of lifts of graded characteristics; a plurality of rotatable wedge lift magazines 55 for containing stacks of wedge lifts arranged in alternate relation; a plurality of reciprocating pushers 56 for producing lifts from the lower ends of the wedge lift magazines; a reciprocating pusher beam 57 for producing a row of lifts from the bottom of the main lift magazines 54 and advancing them in a row to a position of deposit; a continuously operated conveyer 58 arranged adjacent to and parallel with the row of main lift magazines and upon which the row of lifts produced therefrom are deposited and by means of which they are fed serially to the pasting apparatus; a plurality of frictional positioning devices 59 associated with the several magazines for imposing a restraint upon the several lifts as they are advanced by the pusher beam 57 and holding them free of the conveyer 58 until substantially the whole of each of the lifts overhangs it, at which time the lifts are permitted to drop into position without disarrangement or skewing thereof; a plurality of lift arresting and positioning fingers 60 for engaging the breast edges of the row of lifts deposited upon the conveyer 58 and temporarily arresting their movement in order to effect their proper alinement; a removable paste pot 61, including a paste roll 62, disposed at the left hand end of the machine and adjacent the end of the continuously operated conveyer 58 for applying paste to the lifts as they are fed serially over the paste roll; a paste tank or reservoir 63 disposed above the paste pot 61 for supplying paste thereto; a plurality of continuously operated feed wheels 64 disposed above the paste pot 61 and at the end of the conveyer 58 for taking control of the

lifts while still upon the conveyer, feeding them over the paste roll 62 and depositing them in superposed relation in the form of a heel-pile; a base-lift magazine 65 for containing a stack of lifts which are to be utilized as lifts for one end of the heels to be built; a transverse conveyer 66 for producing lifts from the base-lift magazine and advancing them in dry condition to the receiving station at which the pasted lifts are deposited thereon in a pile and for subsequently advancing the heel-pile to a position where it may be removed readily by the operator; and a heel rotating device 67 carried by the supporting frame of the transverse conveyer 66 and actuated by the movements thereof, for raising the heel-pile advanced into the removal position above the conveyer and rotating it through a quarter turn to a suitable position it for ready removal and transfer by the operator to the alining, pressing and nailing mechanism 52.

The supporting frame of the lift-assembling mechanism comprises a plurality of end pedestals 70 and 71, which are mounted upon the main supporting bed 53 and which carry the supporting table 72, which is suitably bolted in position between them. The end pedestals 70 and 71 are also rigidly connected by means of a curved front plate 74 and a rear plate 75.

Power is supplied to the machine by a belt 73 from any suitable source through the agency of the usual fast and loose pulleys 76 and 77, which are loosely mounted upon the right hand end of a normally idle cam shaft 78 upon which are mounted a plurality of cams 79, 80, 81, 308 and 320 for governing the operation of certain actuating mechanisms of the machine. For controlling the supply of power to the machine, a belt shifter 82 (Figs. 1 and 2) of any ordinary form is employed and is secured to the end of a shift rod 83 that extends horizontally across the front of the machine and is provided with a handle 84 in a position convenient to be grasped by the operator.

The fast pulley 76, while loosely mounted upon the cam shaft 78 is rigidly associated with a pinion 85 that meshes with a gear 86 which is secured to the end of a jack shaft 87 that is suitably journaled in the end pedestals 70 and 71 of the supporting frame. A pinion 88 is fixed to the jack shaft 87 and meshes with a gear 89 that is fixed to an extended hub of a clutch disk 90 (Figs. 1 and 7) which is loosely mounted on the cam shaft 78. The clutch disk 90 is provided with a series of lateral projections or teeth 91 with which a cooperating clutch lever 92 is adapted for engagement. The clutch lever 92 (Figs. 6 and 7) is bifurcated at its lower end to straddle a sleeve 93 and is pivotally mounted upon

a pin 94 that projects through the bifurcated ends of the lever, through the sleeve 93 and through the cam shaft 78. The clutch lever 92 is normally urged by means 5 of a spring 95 into operative position to engage one of the lateral projections of the clutch disk 90, but, as shown in Fig. 7, is held in inoperative position out of engagement therewith by means of a wedge 10 cam member 96 (Fig. 8). This member 96 is pinned to a transverse rod 97, which extends to the front of the machine and is provided with a handle 98, by which the operator may conveniently release the clutch 15 lever 92 to cause the clutch to be thrown in and the cam shaft 78 to be thereby connected to the source of power. The rod 97 is suitably journaled in the front plate 74 and in a bracket 99 (Fig. 6) which is 20 secured to the rear plate 75 of the frame, and near its rear end the rod 97 is provided with an arm 100 to which one end of a spring 101 is attached, the other end being fixed to a stationary pin 102 that 25 projects outwardly from the bracket 99. The spring 101 therefore acts to normally maintain the wedge cam 96 in its operative position, as shown in Fig. 7, in which position the end of the clutch lever 92, during its rotating movement, is brought into engagement with the inclined cam surface 103 thereof, which serves to force the cam lever out of engagement with the projections 90 of the rotating clutch disk 90. A 30 stop pin 104 is provided in the bracket 99 for engaging a portion of the arm 100 to limit the movement of the rod 97 and wedge cam 96.

A similar wedge cam 105 is provided 40 up on a rod 106 disposed parallel to the rod 97 and below the clutch disk 90, and concurrent operations of the two wedge cams 96 and 105 are effected by means of a connecting equalizing link 107 that is pivotally 45 associated with arms 108 and 109 (Figs. 6 and 7) that are respectively fixed to the transverse rods 97 and 106.

In order to retain the wedge cams 96 and 50 105 of the clutch in their inoperative positions, the rod 106 is provided with a depending latch arm 110 which is adapted to cooperate with a shoulder of a latch 111 when the wedge cams are released by the operator. The latch 111 is in the form of 55 a bell crank, being pivotally mounted upon a stud 112, and is biased to its latching position by means of a spring 113. The wedge cams 96 and 105 are therefore latched in their inoperative positions, after being actuated into said positions by the operator, until such time as the latch 111 is released. This is accomplished after a half revolution 60 of the cam shaft 78 by means of one of two cam lugs 114 (Figs. 6 and 7) that 65 are provided upon the side of the cam 80

and which cooperatively engage a cam roll 115 that is carried by the upper arm of the bell crank latch 111. Such engagement actuates the latch 111 to disengage the latch arm 110, whereby the rods 97 and 106 and 70 their associated wedge cams 96 and 105 are free to be actuated by means of the spring 101 into their operative positions, in which their cam surfaces 103 are engaged by the rotating clutch lever 92. The clutch 75 lever 92 is thus forced to its outer inoperative position to disengage the projections 91 of the clutch disk and disconnect the power from the cam shaft 78.

The provision of two similar wedge cams 80 96 and 105 is rendered necessary for the reason that the various cams 79, 81, 308 and 320 of the machine are designed to effect a complete cycle of operation of their associated mechanisms in a half revolution of the 85 cams. In other words, the cams are of the two cycle type and are adapted to effect two complete cycles of operation for every complete revolution thereof. The machine, however, is a single cycle machine and its operation is automatically arrested after each 90 complete cycle by means of the automatic clutch hereinbefore described, it being evident that after the wedge cams 96 and 105 are moved to their inoperative position, 95 thereby permitting the clutch to be thrown in, said cams are latched in such position temporarily, until subsequently released by one of the cam lugs 114 on the cam 80, which occurs after a half revolution has 100 been effected. Upon the release of the wedge cams, they are immediately restored to operative position such that the rotating clutch lever 92 is brought into engagement with the lower wedge cam 105 after a half revolution 105 has been completed, whereupon the disengagement of the clutch is effected in the manner already set forth.

Having described the general construction of the supporting frame of the machine 110 and the manner of supplying power and controlling the operation of the main cam shaft thereof, the construction and operation of those component parts of the machine which are operated by means of the several cams 115 will now be set forth.

In an automatic heel building machine, it is necessary to make provision for holding stacks of lifts from which the heels are built and, for this purpose, the main magazines 120 54 are provided. These magazines are formed by a plurality of members or partitions 117 (Figs. 1, 2 and 10) that are vertically disposed and are adjustably positioned longitudinally of the machine upon pairs of horizontal channel members 118 that are secured to the forward ends of the end pedestals 70 and 71. Each of the magazine members or partitions 117 conveniently comprises 125 a pair of angle members 119 which are con- 130

- connected by means of a strip 120 of sheet material. The forward angle member 119 of each of the magazine partitions is provided with a pair of forwardly projecting bolts 121 which extend through the spaces between the supporting angle members 118 and are provided with channel shaped clamps 122 that cooperate therewith and are firmly clamped thereto by means of wing nuts 123.
- 10 The several magazine partitions 117 are adjustable longitudinally along the supporting members 118 and may be spaced apart any desired distances for the purpose of accommodating stacks of lifts of graded sizes.
- 15 Since any partition 117 may constitute a common part of two adjacent magazines, it is clear that the magazines may be grouped together in a minimum amount of space, while being located in any position with respect to the length of the machine.
- In order to enable wedge heels to be built, a plurality of auxiliary wedge lift magazines 55 are provided, and these magazines are adapted to contain stacks of wedge lifts that 25 are disposed in alternate arrangement with their breast edges transverse to the machine. These magazines are located out of alignment with and behind the row of main magazines 54 and are adjustable longitudinally 30 of the machine to permit them to be properly located with respect to the other magazines, so that the wedge lifts produced therefrom, shall occupy any desired positions relative to the lifts produced from the main 35 magazines. The arrangement of magazines shown in Figs. 1 and 2 is such that the second and fourth lifts in the heels to be built shall be wedge lifts. The main magazines and the wedge lift magazines, therefore, are 40 relatively positioned so that wedge lifts produced from the wedge lift magazines located behind the row of main magazines may be advanced through suitable spaces in the row of main magazines.
- 45 To provide for the longitudinal adjustment and position of the wedge lift magazines 55, each of these magazines is mounted upon a carriage 125 (Figs. 6 and 13) which is slidably and adjustably mounted upon 50 supporting rods 126 and 127 that are disposed lengthwise of the machine and are carried by the respective end pedestals. The carriage 125 is provided with a vertically located shaft 128 which is surrounded by a 55 sleeve 129 and a pinion 130 that are pinned thereto. The shaft 128 is shorter than the sleeve 129 and its upper end is provided with a tongue 131 that is semi-cylindrical in form.
- The wedge lift magazine 55 is box-like in 60 structure, having an opening 132 (Figs. 13 and 15) extending vertically through one of its sides to permit of the insertion of the operator's fingers in loading the lifts into the magazine, and this box-like magazine is carried between the arms of a channel shaped

yoke 133 to which it is suitably attached, filler blocks 134 being provided between the magazine and the supporting yoke to enable magazines of different sizes to be employed. A plate 135 is secured to the lower end of 70 the magazine above the supporting yoke 133 and constitutes the bottom thereof, and immediately above this bottom plate the magazine is provided with recesses 136 in opposite sides thereof, through which the lifts 75 are successively removed.

In order to support the magazine upon the carriage 125, a centrally located pin 137 (Fig. 15) is secured to the lower side of the yoke 133 and is adapted to be set into the 80 enlarged head of the sleeve 129 that is mounted in the carriage 125. The lower end of the pin 137 is provided with a semi-cylindrical portion 138 which is the complement of the similar portion 131 of the shaft 128, and these two complementary semi-cylindrical projections cooperate, the one with the other, to provide a driving connection so that any rotative movements that are imparted to the pinion 130 and therefore to the shaft 128, are transmitted through the pin 137 to the wedge lift magazine 55. By reason of this construction, it is evident that the rotatable wedge lift magazine 55 may be 85 conveniently removed from the carriage 125, if desired.

Inasmuch as the wedge lifts are stacked in alternate relation in the wedge lift magazines, as shown in Fig. 15, it is necessary 90 that the magazines be rotated through a half-turn at each cycle of operation of the machine in order that the wedge lifts produced therefrom shall occupy similar positions with respect to their breast edges. To accomplish this result, each carriage 125 is 95 provided with a reciprocating rack 139 (Figs. 6, 13 and 14) which engages with the pinion 130. The rear end of the rack 139 is provided with an open slot 140 to receive a longitudinally disposed rod 141 which is 100 carried at the upper ends of two arms 142 and 143 (Fig. 2), that project upwardly from a sleeve 144, which is rotatably mounted upon a crank shaft 145. The arm 142 constitutes a part of a bell crank, the other arm 146 (Fig. 6), of which carries a roll 147 that traverses in a path 148 in the cam 80 that is mounted upon the cam shaft 78. The cam 80 is a single cycle cam and is designed 105 so that as it is actuated through each half revolution, the racks 139 having operative connections with the rod 141, are moved forward during one cycle of operations of the machine and moved back through the succeeding cycle thereof. During each of these 110 actuating movements of the racks 139, the several wedge lift magazines are rotated through 180°, first in one direction and then in the other, to properly position the lowermost lifts in the magazines, so that they may 115

be removed and shall occupy definite and similar positions with respect to the lifts of the main magazines.

In order to remove the lowermost wedge lifts at each cycle of the machine, and at each half revolution of the magazines, the pushers 56 (Figs. 6 and 13) are provided, and these pushers are severally mounted upon the respective carriages 125 and are adapted to be reciprocated in timed cooperation with the rotation of the magazines to engage and eject the lowermost wedge lifts therefrom. Each of these pushers 56 is slidably mounted between ways 150 on the rearward portion of its carriage 125 and in the plane of the recess 136 provided at the lowermost end of the rotatable magazine. The forward extremity of each pusher is curved in contour to conform to the shape of the lifts and that portion of the forward end of the pusher which is projected through the magazine recess is wedge-shaped in section to correspond to the wedge form of the lifts. The rear end of the pusher is provided with a boss 151 carrying a pin 152 upon which a slotted member 153 is rotatably mounted. This member is normally held in upright position, as shown in Fig. 6, by a torsional spring 154, in order to receive a rod 155 by means of which the pushers are reciprocated, but may be tilted down against the action of the torsion spring 154 to effect the disengagement of the pusher with the actuating rod 155.

The rod 155 is carried at the ends of upright arms 156 and 157 (Figs. 2 and 6) which are rigidly united by means of a semi-cylindrical connecting yoke 158 that straddles the sleeve 144 to which are associated the arms for actuating the racks 139. The arm 157 is provided with a laterally projecting boss 159 (Fig. 5) which cooperatively engages a boss 160 that is provided upon a lever 161 which is rotatably mounted upon the shaft 145. The outer end of the lever 161 carries a roll 162 which travels in a cam path 163 in the cam 81 that is mounted upon the cam shaft 78. In order to provide a yielding element in the advance movement of the pushers 56, whereby the operating mechanism may be protected against injury in case undue resistance is encountered, the lever 161 and arm 157 are connected through the agency of a coiled spring 164 which surrounds a rod 165, that projects through registering openings in the bosses 159 and 160, the spring being confined between the head 166 of the rod and the boss 160, and the rod being rigidly held in place in a suitable manner.

The cam 81 is a two cycle cam and each half revolution thereof causes the pushers 56 to be reciprocated once and returned to their initial inoperative positions, as shown in Fig. 5. Moreover, the cam 81 is angular-

ly positioned with respect to the cam 80 so that the pushers 56 are advanced to produce lifts from the wedge lift magazines 55 only after said magazines have been rotated through a half turn and are at rest. In Fig. 13 one of the pushers 56 is illustrated in its foremost position, having been projected through the recess at the bottom of the wedge lift magazine to produce a lift therefrom.

During the production of a wedge lift from its magazine, it is necessary to confine the lift and maintain it under control in order that it shall not be displaced in position, and therefore, a guiding finger 168 (Figs. 6 and 13) is provided in front of each rotary magazine and so positioned as to hold down the lift as it is advanced from the magazine by the pusher. Each guiding finger 168 is pivoted about a screw 169 which is carried by a plate 170 that is secured to the lower end of a rod 171, the latter being mounted for vertical movement only in guide arms 172 of a U shaped bracket that is secured to a vertically disposed supporting bar 173. This bar is provided with a forwardly projecting pin 174 and is adjustably secured to the lower pair of horizontally disposed supporting angle members 118 in the same manner as the adjustable magazine partitions 117. The forward end of the plate 170 is provided with a lateral extension which is wedge shaped in cross section to conform to the inclination of the wedge lifts. This plate is resiliently held in engagement with the lifts as they are advanced by means of a coiled spring 176 which surrounds the supporting rod 171 and is located between the upper arm 172 of the supporting yoke and a collar 177 that is pinned to the rod 171. The plate 170 is held in position against rotative movements by means of a pin 175 carried by the plate and projecting through an opening in the lower arm 172 of the supporting yoke.

The pivotally mounted guide plate 168 for holding down the lifts as they are produced from the wedge magazine is located immediately in front of the magazine and in such position that as the magazine is oscillated in the one direction or the other in the manner already described, the guide plate 168 is engaged thereby and swung about its pivot to permit the magazine to turn. As soon as the magazine has been rotated past the guide plate 168, a spring 179 which is secured between a pin 180 in the plate and an arm 181 projecting rearwardly from the collar 177 functions to return the guide plate 168 to its normal position where it is in readiness to cooperate with and control the production of the next wedge lift ejected from the magazine.

The wedge lifts produced from the wedge

lift magazines 55 and advanced to the position indicated in Fig. 13 in the manner just described, are subsequently advanced forwardly by means of the reciprocating 5 pusher beam 57 (Figs. 2 and 11), which is reciprocated across the upper surface of the table 72 and beneath the row of main lift magazines 54 from which it ejects or produces a row of lifts, one from each magazine, and advances them in a row to a position of deposit. The pusher beam 57 extends longitudinally of the machine and is substantially the length of the table 72. Normally, the pusher beam is located behind 10 the row of main lift magazines, in the position indicated in Figs. 2 and 13, in which position it is also behind the wedge lifts that have been produced from the wedge lift magazines.

20 The reciprocation of the pusher beam 57 is effected by means of a parallel motion mechanism that is connected to and is operated by one of the rotative wedge lift magazines, the beam being advanced and 25 retracted to its initial position during each rotation of the wedge lift magazine. To effect this operation, an arm 185 (Figs. 6 and 13) is fixed to the sleeve 129 upon which the wedge lift magazine rests, and 30 this arm is connected by a link 186 (Figs. 2, 11 and 13) to an intermediate point of an arm of a bell crank 187. This bell crank is pivotally mounted upon a stud 188 projecting downwardly from the table 72, its 35 long arm being connected by a link 189 to one end of the pusher beam 57, and its short arm having a pivotal connection to a link 190 that is also pivotally connected to the short arm of a similar bell crank 191. 40 This bell crank 191 is rotatably mounted upon a fixed stud 192 that projects downwardly from the table and the long arm thereof is connected by a link 193 to the other end of the pusher beam. This arrangement of links and bell cranks constitutes 45 the parallel motion mechanism hereinbefore referred to, and by reason of its connection with one of the rotatable wedge lift magazines, is actuated during each half 50 rotation thereof, to first advance the wedge lifts already produced, together with a series of lifts from the main magazines, to a position in which the entire row of lifts is deposited and then is retracted to its 55 normal position, as shown in Figs. 2 and 13. The forward position of the pusher beam 57 is such that the major portion of the beam occupies a position beneath the row of main lift magazines so that the 60 stacks of lifts contained therein are sustained thereby until the beam is again retracted at which time the stacks are allowed to drop until their lowermost lifts rest upon the table 72.

65 The series of lifts thus produced from

the wedge lift and main magazines are deposited in a row upon the continuously moving conveyer 58, which is located immediately adjacent and in front of the row of main lift magazines and in parallel relation 70 therewith. This conveyer 58 is preferably in the form of an endless belt which may conveniently be of canvas, leather, or like material and is carried at its ends upon a pair of pulleys 195 and 196 (Fig. 1), which 75 are located at the respective ends of the machine. The upper stretch of the conveyer 58 travels over and is supported by the table 72 which is recessed along its front portion (Fig. 10), to a sufficient extent to bring the 80 upper surface of the conveyer a slight distance below the main or rear portion of the table so that the lifts produced from the magazines may be advanced across the table and deposited upon the upper stretch of the 85 conveyer. The pulley 195 is suitably mounted upon a bracket at the left hand end of the machine, while the pulley 196 is carried at the right hand end of the machine upon a pivotally mounted arm 197 which cooperates with a spring 198 for the purpose of maintaining the conveyer under tension.

Although the conveyer 58 may be advanced intermittently, it is preferably continuously operated, and to accomplish this 90 result the pulley 195 is fixed to a shaft 199 (Figs. 4, 16 and 17) to the opposite end of which a bevel gear 200 is attached. This gear cooperates with a bevel gear 201 (Fig. 4) which is carried at the upper end of a 100 vertical shaft 202, the lower end of which is provided with a bevel gear 203 which meshes with a bevel gear 204 that is fixed to the jack shaft 87. Inasmuch as the jack shaft 87 rotates continuously so long as 105 power is supplied to the machine, it is evident that the conveyer 58 is also continuously actuated through the drive mechanism just described.

An important feature of the invention resides in the use of a conveyer extending the length of the machine and having an uninterrupted plane surface, upon which the row of lifts produced from the magazines is deposited, it being manifest that 110 with a conveyer of this type, the lifts may be deposited upon it in any position whatsoever, thereby permitting the magazines of the machine to be longitudinally adjusted in any spaced relation desired, without reference to the conveyer itself. This freedom of adjustment and location of the magazines, rendered possible by the use of an uninterrupted belt conveyer, not only permits the magazines to be adjusted with 115 facility but permits them to be grouped together in a minimum space for any particular type of heel that is to be built, and moreover, permits this group of magazines to be located near the left hand end of the 120 125 130

machine so that the lifts deposited thereon are fed through a minimum distance thereby.

In advancing the lifts from the magazines across the table 72 and into position upon the moving conveyer 58, it is desirable to make provision for maintaining the lifts above and out of contact with the moving conveyer until substantially the whole of all of the lifts are advanced into a position in which they overhang the conveyer, it being evident that if the lifts were allowed to touch the conveyer as they were advanced, the rapid movement of the conveyer would tend to drag the lifts in the direction of its movement and thus cause them to be skewed with respect to their breast edges or perhaps to be disarranged entirely. Therefore, the forward angle iron 119 of each of the magazine partitions 117 is provided with a frictional positioning device 59, which comprises a friction block 207 that is carried by a rod 208 slidably mounted for vertical movement between suitable lugs 209 with which the angle member is provided. A spring 210 surrounds the rod between the upper lug and a fixed collar 211 and serves to hold the block 207 down into frictional engagement with the lift as it is advanced under it. The lower surface of the friction block 207 is tapered rearwardly and upwardly in order to permit the lift to be moved under it without obstruction, and said friction block 207 is located immediately adjacent the recessed front portion of the table 72 so that it maintains a frictional pressure upon the lift as it is advanced and thus holds it in substantially the plane of the table and out of contact with the moving conveyer until the lift is positioned substantially above the conveyer and may be dropped thereon quickly and without any disarrangement of position.

A similar function is performed upon the wedge lifts by means of the spring-pressed tapered friction plates 170 that are secured to the horizontally disposed supporting angle members 118 in a position in front of the wedge lift magazines as already described.

In the event that particular accuracy is desired in positioning the lifts upon the moving conveyer 58 to secure an exact parallel alinement of the breast edges thereof, means in addition to the frictional positioning devices just described may be provided for temporarily engaging the breast edges of the several lifts and arresting their movement for a brief interval during the continued operation of the conveyer whereby all of the lifts are accurately alined before the arresting means is withdrawn to permit the series of lifts to be carried away by the moving conveyer.

To the accomplishment of this result, a

plurality of fingers 60 (Figs. 1, 2, 10 and 12) are provided which are pivotally mounted upon the front edge of the table 72 and are normally adapted to rest upon the upper surface of the moving conveyer.

The several arresting fingers 60 are of like construction and each is located directly opposite one of the magazine partitions 117, being adjustable longitudinally of the machine so that they may be spaced in accordance with the spacing of the lift magazines. The adjustability of the lift arresting fingers 60, while permitting their pivotal movement is secured by the following construction. The front edge of the table 72 is provided with a longitudinal groove 215 (Figs. 10 and 12), which is partially enclosed by guide strips 216 that are screwed to the table, thus forming a way to receive the heads of horizontal pivot bolts 217 that project through bushings 218 upon which the fingers 60 are pivotally mounted. The bushings 218 are of slightly greater length than those portions of the fingers which surround the bushings and, therefore, the pivot bolts 217 may be rigidly secured in place by means of suitable wing nuts 219 which act against the front ends of the bushings, but which leave the fingers 60 free for pivotal movement. The fingers 60 extend substantially across the entire width of the moving conveyer 58, and adjustably secured to the right hand side of each of the fingers is an angle member 220 for assisting in positioning the lifts upon the conveyer.

For the purpose of raising the fingers 60 from their operative lift arresting positions immediately over the conveyer, each of the fingers is provided with a downwardly extending lug 222 which is adapted to rest upon a longitudinally disposed actuating rod 223 that is supported at its respective ends upon arms 224 that are pivotally mounted upon the main supporting frame of the machine. The actuating rod 223 normally occupies the position shown in Fig. 1, in which position the lift arresting fingers 60 are permitted to occupy their operative lowered positions. By raising the actuating rod 223 upon which the fingers 60 rest, said fingers are rotated upon their pivots and elevated above the conveyer. This operation is effected through the agency of a shaft 225 (Figs. 1 and 6) upon which the left hand supporting arm 224 is mounted and which carries at its rear end a horizontal arm 226 that is connected by a universal joint 227 to the upper end of a vertical rod 228. The lower end of this rod is connected by a universal joint 229 to one arm 230 of a bell crank that is mounted on the crank shaft 145 and having another arm 231 (Figs. 3 and 4) which carries a roll 232 that cooperatively engages the cam 79. This cam is designed to permit the lift arresting fingers

- 60 to normally occupy their operative positions until the series of lifts has been produced from the magazines and deposited upon the conveyer. After the lifts have been 5 restrained temporarily to permit an accurate alinement thereof, the cam 79 causes the supporting and actuating rod 223 to raise the fingers from the conveyer for a brief interval during which the lifts are fed.
- 10 After having produced a series of lifts from the magazines and deposited them in a row upon the moving conveyer, the conveyer advances or feeds the lifts serially toward the paste pot 61 which is located adjacent 15 the left hand end thereof, with its upper surface in the plane of the upper stretch of said conveyer. The paste pot 61 is removably mounted on ways 238 (Figs. 16 and 21) that are formed on a bracket 239 that is suitably secured to the end pedestal 70 of the machine. The paste pot comprises a rectangular tank that is adapted to slide into position on the ways 238 and is provided with a downwardly projecting portion 240 that carries a handle 241 which is pivoted upon a pin 242. This handle 241 is bifurcated in form and its spaced ends constitute locking members 243 which, in the operative position of the paste pot, are rotated into a slight depression 244 in the lower sides of the ways 238 for the purpose of locking the paste pot firmly in position. When the handle 241 is manipulated to disengage the locking members from the depressions 244, said handle may be employed to pull the paste pot from its position so that it may be removed for purposes of cleaning.
- The paste pot 61 is provided with a cover 246 that may be readily removed to permit 40 access to the corrugated paste roll 62 which is rotatably mounted within the paste pot and which projects upwardly through an opening 247 in the cover 246 to a distance sufficient to engage the lower surfaces of any lifts that are fed across it and to apply a coating of paste thereto. The paste roll 62 is fixed to a shaft 249 that is journaled in one end of the paste pot and an intermediate partition 250 that extends between the upper portions of the sides thereof. In cooperative engagement with the lower side of the paste roll 62 is a paste feed roll 251 that is immersed in the paste within the paste pot and which is rotatably mounted to carry paste to the paste roll. The paste feed roll 251 is fixed to a shaft 252, one end of which is journaled in the intermediate partition 250 and the other end thereof is provided with a central recess to receive a bearing pin 253 that projects inwardly from a stud 254 which is threaded into the end of the paste pot and which is firmly and tightly held in position by means of a lock nut 255. This mode of mounting the shaft 252 of the paste applying roll which is always im-

mersed in the paste, insures a tight joint that prevents leakage.

The paste roll 62 and paste applying roll 251 are continuously driven by pinions 257 and 258 that are respectively provided upon the rear ends of the shafts 249 and 252, and which mesh with an intermediate pinion 259 carried upon a shaft 260 that is suitably journaled in the intermediate partition 250 and in the opposite end of the paste pot. The outer end of the shaft 260 carries a pinion 261 (Figs. 4, 17 and 19), that meshes with a gear 262 that is fixed to the continuously rotating shaft 199 that carries the conveyor pulley 195. The paste roll 62 and its paste feed roll 251, therefore, are driven continuously so long as power is supplied to the machine. Obviously, when the paste pot is removed from the machine, the pinion 261 is slid out of mesh with the driving gear 262.

In order to prevent an excess of paste from being carried upwardly by the paste roll, a suitable scraper 263, (Fig. 21) is provided which functions in the usual way. The paste pot is supplied with a quick drying paste from the paste reservoir 63 which is suitably supported above it and which is connected thereto by means of a conduit 264 that projects downwardly into the paste pot through an opening 265 in the paste pot cover 246. This conduit must, of course, be withdrawn from the paste pot before the paste pot and roll can be removed bodily from the machine.

The paste pot and roll are positioned in the machine in such manner that paste is not distributed over the machine but is confined to the paste pot and roll, which are relatively small and are so constructed and arranged that they may be removed as a unit for purposes of cleaning.

Inasmuch as the paste pot and paste roll are located adjacent the end of the conveyer 58, it is necessary to provide additional feeding means for advancing the lifts supplied by the conveyer over the paste roll 62, and this means comprises a set of feed wheels 64 which are located above the paste pot and paste roll and which are so arranged as to engage and take control of the successive lifts fed by the conveyer while said lifts are still carried thereby, so that the lifts are always maintained under control and in proper alinement.

The several feed wheels 64 are mounted upon shafts 268 that are disposed in parallel relation transversely to the conveyer 58. The first shaft 268 is located directly above the conveyer pulley 195 and carries a single feed wheel; the second and fourth shafts 268 carry two feed wheels; the third shaft is provided with five feed wheels, while the last shaft carries a single feed wheel, which, moreover, is located below the plane

of the other feed wheels. The spacing of the several feed wheel shafts 268 is such that the staggered feed wheels 64 are located in overlapping relation so that the feed 5 wheels of one shaft engage and take control of each lift before it is disengaged from the wheels of the preceding shaft, whereby continuous feeding of the lifts is assured. Each of the feed wheel shafts 268 is carried 10 in a U-shaped supporting yoke 269 (Figs. 4 and 16) to which is rigidly attached an upwardly projecting rod 270. The rods 270 that are associated with the first four supporting yokes 269 project upwardly through 15 openings 271 in a bracket member 272 and are yieldingly pressed down into engagement with the lifts by springs 273 that surround the rods within said openings and which are disposed between the upper ends 20 of the openings and shoulders 274 near the lower ends of the rods. Pins 275 project through the upper ends of the rods and limit their downward movement. The first 25 four sets of feed wheels, therefore, are independently and yieldingly mounted and are adapted to be raised and lowered in position as the successive lifts are advanced. The upwardly projecting rod 270 associated with the supporting yoke 269 of the last feed 30 wheel shaft, however, is rigidly secured to the supporting bracket 272 in such position that the feed wheel is disposed slightly below the plane of the other feed wheels, as shown in Fig. 16.

35 In order to guide the supporting yokes and feed wheels and maintain them in proper alignment during their yielding vertical movement, a supporting and guiding member 277 (Figs. 4 and 16) is bolted to the end pedestal 70 and embodies a vertically extending guide plate 278 which is provided with a series of open ended slots 279 for the reception of journal blocks 280 with which the several feed wheel shafts 268 are provided.

40 The several sets of feed wheels 64 are continuously driven in the direction indicated by the arrows (Fig. 16), and in order to permit the yielding relative vertical movements of the several sets of feed wheels during the feeding of successive lifts across the paste roll, the several shafts 268 are associated through the agency of flexible shaft sections 282 (Figs. 4 and 18) with other shafts 45 283 that are rotatably mounted upon fixed axes in a supporting bracket 284. This bracket is bolted to the end pedestal 70 of the machine and, in conjunction with the supporting angle member 277, serves to 50 carry the supporting bracket 272, as shown in Fig. 4. The outer ends of the several shafts 283 are provided with pinions 285 (Fig. 17), which are connected together by a plurality of idler gears 286 to be driven 55 concurrently. It is desirable that the last

feed wheel which is fixed in position be relatively small and be driven at a greater speed than the other feed wheels, in order to quickly feed the lifts into assembling position, and, therefore, its driving pinion 285 is smaller than the other similar pinions, as 60 illustrated in Fig. 17.

65 The gearing just described, is driven from the first shaft 283 which is provided with a gear 287 that meshes with a gear 288 which is carried by the continuously rotating shaft 199 that drives the belt conveyer 58 and also the paste roll 62. The several sets of feed wheels, therefore, are driven continuously 70 so long as power is supplied to the machine 75 and they serve to take control of and feed the lifts in rapid succession across the paste pot 61 and feed roll 62 as they are supplied by the continuously operated conveyer 58.

80 From the foregoing description it is seen how a series of lifts is produced from the lift magazines and deposited in a row in dispersed relation upon the continuously moving conveyer 58 which carries them serially 85 to the feed wheels 64. The feed wheels take 90 control of the lifts successively, while they are still upon the conveyer and advance them in rapid succession over the paste roll 62, during which movement the lower surface of each of the lifts is coated with a thin 95 film of quick drying paste.

95 The next step in the building operation is to immediately assemble the freshly pasted lifts in rapid succession into the form of a heel or heel-pile before the paste has had 100 a chance to set or lose any of its adhesive qualities. The feed wheels 64, and particularly the last rigidly supported feed wheel, assist in this assembling of the pasted lifts in superposed relation in a manner to be 105 hereinafter set forth.

110 Before explaining the assembling operation, however, a description will be given of the means for producing a base lift from the base lift magazine 65 and advancing it 110 into assembling position adjacent the paste pot 61 and in alignment with the conveyer 58 so that the pasted lifts may be superposed upon it to form a heel.

115 In order to produce a resultant heel having a dry lower surface, it is necessary to so locate the base lift magazine that the lifts produced therefrom shall be advanced into assembling position through a path that is entirely free of paste. This path, therefore, 120 must be different and independent from that which is traversed by the series of pasted lifts. The base lift magazine 65, therefore, is located out of alignment with and behind the row of main magazines 54 and on the 125 opposite side of the paste roll 62, as shown in Figs. 1 and 2.

130 The base lift magazine 65 is box-like in form and is mounted in substantially vertical position upon an end member 290

(Figs. 4 and 9) of a supporting frame 291 that extends transversely of the machine and is located at the left hand end thereof adjacent to the paste pot 61. The frame 291 also comprises another end member 292 which is connected to the first member 290 by means of a plurality of strips or bars 293 and 294, said bars being suitably secured to the top and bottom surfaces of the respective end members.

This supporting frame 291 which is pivotally mounted at its rear end upon a shaft 295 that is carried by and fixed to the end member 290, is so positioned as to lie directly under the last rigidly mounted feed wheel 64, as shown in Fig. 16. Near the forward end of the supporting frame 291, a breast plate 296 is secured to the upper bar 293 and extends upwardly at substantially right angles to the upper surface of said bar. The breast plate 296 is located in alinement with the moving conveyer 58 and paste roll 62 and, in conjunction with the upper bar 293 of the supporting frame, constitutes a receiving device into which the component lifts of the heel are assembled by the feed wheels 64 in superposed relation with their breast edges in engagement with said breast plate.

The shaft 295 (Fig. 4), about which the supporting or receiving frame 291 pivots, is rotatably carried by a yoke 298 having a substantially horizontal pin 299 that projects through and is adjustably secured to the slotted upper end of an upwardly curved bracket 300 which is suitably bolted to the end pedestal 70 of the machine. This shaft 295 which is fixed to the end member 290, projects towards the end pedestal 70 and carries at its outer end a downwardly projecting arm 302 (Figs. 1, 3, 4 and 6) that is fixed thereto.

Referring particularly to Fig. 4, the lower end of the arm 302 is connected by a strong and closely wound spring 303 with the upper end of a lever 304 that is rotatably mounted upon a stud 305 supported in the end pedestal 70 and in a bracket 306 secured thereto. Intermediate the ends of the lever 304 is a pivotally mounted roll 307 which cooperatively engages the cam 308 that is fixed to the cam shaft 78.

During that portion of the cycle of operations in which the several pasted lifts are delivered in rapid succession and in superposed relation into the receiving device and against the breast plate 296, the cam 308 maintains the heavy spring 303 under tension to act through the arm 302 to yieldingly hold up the supporting frame 291 of the receiving device. As the pasted lifts are successively delivered in superposed relation into the receiving device by means of the feed wheels 64, and particularly by the last rigidly supported feed wheel, said re-

ceiving device is progressively forced downwardly about its pivot against the action of the spring 303 to accommodate the progressively increasing height of the heel-pile being assembled.

The cam 308 is so designed that after the assembling of the lifts in the manner just referred to has been accomplished, the lever 304 is permitted to swing inwardly towards the cam shaft, thereby releasing the tension of the heavy and closely wound spring 303 and permitting the receiving device to drop slightly through the action of gravity, to free the uppermost lift of the pile from engagement with the rigidly supported feed wheel 64 located directly above it. The weight of the receiving device is insufficient to stretch the spring 303, which in its normal closely wound condition, serves to definitely locate the receiving device in its partially lowered position in accordance with the action of the cam 308.

The base lifts stacked in the magazine 65 are produced therefrom successively and advanced into the assembling position adjacent the breast plate 296 by means of the transverse endless conveyer 66 which is carried upon pulleys 310 and 311 (Fig. 4) that are pivotally mounted in the respective end members 290 and 292 of the supporting frame or receiving device. The pulley 311, located at the front end of the supporting frame, is adjustably positioned in such manner that the conveyer may be tightened at will. This conveyer 66 is preferably made of canvas, leather or other suitable belting material and is provided with a plurality of cross pieces 312 that are spaced at predetermined intervals thereon. The transverse conveyer 66 passes through openings 313 (Fig. 9) at the bottom of the front and rear walls of the base lift magazine 65 and its upper stretch is supported upon the upper connecting strip or bar 293.

The stack of lifts in the base lift magazine 65 rest upon the transverse conveyer 66 and, as the conveyer is actuated in steps in the manner now to be set forth, the lowermost lifts in the magazine are progressively produced therefrom through the openings 313 by reason of the engagement therewith of the successive cross pieces 312. The base lifts thus produced are advanced in steps by the conveyer 66, one step for each cycle of operation of the machine, into the assembling station adjacent the breast plate 296, and, during this advancing movement, the lifts are retained in position and under control by means of a spring guide 314 that is secured to the magazine 65 and extends forwardly a considerable distance directly above the conveyer in such position as to have a sliding engagement with the advancing lifts.

The step by step movement of the trans-

verse conveyer 66 is effected through the agency of a reciprocating pawl 315 (Fig. 4) which is pivotally mounted at the upper end of an arm 316 and is held upwardly 5 in operative position by means of a spring 317. The arm 316 (Figs. 1 and 4) constitutes a part of a bell crank that is rotatably mounted upon the stud 305 and having another arm 318 carrying a roll 319 that 10 operatively engages the cam 320 that is secured to the cam shaft 78. The cam 320 is designed to permit a spring 321 that is attached to the arm 316 to actuate the pawl 315 during each cycle of operation of the 15 machine. The pawl 315, by reason of its engagement with one of the cross pieces 312 of the transverse conveyer 66, therefore, advances said conveyer through a single step, after which the cam 320 retracts the 20 pawl 315 to a position where it is in readiness to engage the next succeeding cross strip 312 and advance the conveyer another step during the next cycle of operations.

From the foregoing description it will be 25 understood that at each step or advance of the transverse conveyer 66, a dry base lift is presented to the assembling station for the deposition upon it of a series of freshly pasted lifts, and, moreover, at each step, the 30 transverse conveyer 66 advances a heel that has just been assembled to a position where it is more readily accessible for removal by the operator. This stepping of the conveyer moreover is timed to take place after the 35 heel has been assembled in the receiving device and after the receiving device has been partially lowered sufficiently to disengage the upper lift of the heel just completed from the last rigidly supported feed 40 wheel 64.

During the advance of the heel upon the conveyer 66 from the assembling station, the cam 308 permits the receiving device 291 to be dropped further in position, and the 45 heel just assembled is then rotated a quarter turn to position its breast transversely across the conveyer in order that the heel may be removed by the operator in a position convenient for transferal and placement in the 50 lift alining, pressing and nailing mechanism 52 with which the lift assembling mechanism 50 cooperates.

This turning movement of the heel is effected by means of the heel rotating device 55 67 which is mounted near the forward end of the supporting frame or receiving device 291. The heel rotating device 67 comprises a stud 324 (Figs. 23, 24 and 25) that is mounted between the upper and lower connecting bars 293 and 294 of the supporting frame, and upon it is loosely mounted, for both vertical and rotative movement, a pinion 325 with which is associated a member 326 having laterally and upwardly projecting arms 327 and 328. To the upper ends

of said arms are respectively attached a plurality of plates 329 and 330 which, under normal operating conditions, are disposed parallel to the conveyer 66 and slightly below or in the same plane with the upper 70 surface thereof, as shown in Figs. 23 and 24. The pinion 325 and member 326 rest upon ends 332 of a bifurcated arm 333 which constitutes a part of a bell crank that is rotatably mounted upon a pin 334 which 75 is supported by a portion of the end member 292 of the receiving device 291. This bell crank is provided with another arm 335 that extends substantially parallel to the conveyer 66 and is located above a stop arm 80 336 that is attached to and depends from the paste pot 61. Cooperating with the pinion 325 is a gear segment 337 carried on an arm 338 that is pivotally mounted on a stud 339 between the upper and lower 85 connecting bars 293 and 294 and said segment 337 is maintained in the position indicated in Fig. 24 by means of a spring 340 that acts upon an arm 341 associated therewith. For the purpose of actuating 90 the gear segment 337 to effect a quarter turn of the pinion 325 and the associated supporting plates 329 and 330, a lever 342 is connected by a link 343 to the arm 338 and said lever is mounted upon the upper end 95 of a pin 344 carried by the lower connecting bar 294. The opposite end of the pin is fixed to a curved arm 345 which is disposed in the path of movement of the cross strips 322 that are attached to the lower 100 stretch of the transverse conveyer 66, as shown in Fig. 24.

The operation of the heel rotating device 67 is as follows. As the conveyer 66 is being advanced to bring forward the heel just 105 assembled, said heel is positioned over the supporting plates 329 and 330 of the heel rotating device. At this time, the cam 308 permits the partially lowered receiving device 291 to drop to a predetermined lower 110 position whereby the arm 335 is brought into engagement with the stop arm 336. The loosely mounted pinion 325 and the heel supporting plates 329 and 330 associated therewith, are thus actuated to remove the 115 heel from the conveyer 66 a distance sufficient to clear the cross strips 312. After the heel is thus elevated and during the last portion of the advancing movement of the conveyer 66, the arm 345 engages one of the moving lower cross pieces 312 and, by reason thereof, actuates the gear segment 337 to turn the pinion 325 and the associated supporting plates 329 and 330 upon which the heel rests through a quarter revolution 120 and into the position shown in Fig. 25. The heel remains in this position until the transverse conveyer 66 is advanced another step during the next cycle of operation of the machine, and during this period, the heel is 125 130

removed by the operator and placed in the lift alining, pressing and nailing mechanism 52, the construction and operation of which will hereinafter be described.

- 5 Having set forth the construction and mode of operation of the lift-assembling mechanism 50, attention will now be directed to the lift alining, pressing and nailing mechanism 52 which cooperates with 10 the lift-assembling mechanism in a manner to be hereinafter described and which, in conjunction therewith, constitutes the machine of the present invention.

Referring to Figs. 1, 2 and 26 to 43 inclusive, the lift alining, pressing and nailing mechanism 52 comprises, in general, a supporting frame upon which the various parts of the mechanism are mounted; a heel receiving and holding device, comprising a 20 breast plate 350 and a plurality of relatively movable pressure members 351 and 352, in which the loosely assembled heel-piles that are built by the lift-assembling mechanism 50, hereinbefore described, are placed by the 25 operator to be further acted upon; a lift alining form comprising a plurality of alining jaws 353, 354, 355, 356 and 357, for cooperating with the component lifts of the heel to effect their alinement; a pressure applying device 30 including the pressure members 351 and 352, which also constitute parts of the heel receiving and holding device hereinbefore referred to, and which serve to force the preliminarily alined lifts into the alining form and subject them to pressure; a nailing device including a nail driving pin 358 for nailing together the alined and pressed lifts of the heel; and an automatic nail supplying mechanism including a nail holder 359 and a feed 35 tube 360 for supplying nails to the nailing device.

The lift alining, pressing and nailing mechanism 52 is located immediately adjacent the lift-assembling mechanism 50 in order that the operator may conveniently remove the loosely assembled heel-piles produced thereby and place them in the lift alining, pressing and nailing mechanism for its operation thereon. Like the lift-assembling mechanism 50, the lift alining, pressing and nailing mechanism 52 is of the single cycle type, in which the operation is automatically arrested after the completion of each full cycle of operation upon a heel. The mechanism may be adjusted to act upon any type of heel that is built by the lift-assembling mechanism, and is particularly intended to operate upon tapered heels.

The supporting frame of the lift alining, 60 pressing and nailing mechanism 52 comprises lower side frames 363 and 364 which are mounted upon the main supporting bed 53 of the machine as a whole, and disposed above these side frames are upper frame members 65 365 and 366 which are secured thereto and

the forward ends of which are connected by a front plate 367. The upper side frames 365 and 366 carry upon them a cap plate 368 which constitutes the table of the machine. This cap plate 368 is bolted to the upper side 70 frames and to the front plate and its forward portion 369 is relatively narrow and supports the breast plate 350.

Power is supplied to the mechanism from a sprocket 370 that is mounted upon the left 75 hand end of the jack shaft 87 of the lift-assembling mechanism, which jack shaft extends through the space between the two mechanisms and has a bearing 371 that is secured to the lower side frame 364. A chain 372 connects the sprocket 370 with a sprocket 373 that is keyed to a cam shaft 374 of the alining, pressing and nailing mechanism. This cam shaft 374 is journaled in the upper 80 side frames 365 and 366 and is continuously 85 driven so long as power is supplied to the lift-assembling mechanism 50.

The operation of the alining, pressing and nailing mechanism 52 is controlled through the agency of a clutch which comprises a 90 clutch disk 375 fixed to the cam shaft 374 and having lateral projections or teeth 376 similar to those of the clutch disk already described. A clutch lever 378 (Figs. 28 and 32) cooperates with the rotating clutch disk 95 375 and is in the form of a yoke, which is pivotally mounted upon a pin 379, which extends through the hub portion of a cam 380 keyed to a loosely mounted sleeve 381 (Figs. 32 and 34) that extends to the left the entire 100 width of the mechanism and which carries a plurality of cams 382, 383 and 384 that are also keyed thereto.

The clutch lever 378 is normally urged 105 into operative position in engagement with one of the clutch disk projections 376 by means of a spring 385, and its disconnection therefrom is effected after each complete revolution thereof, by means of a wedge cam 386 which forms a part of a control arm 387 110 that is pivotally mounted upon a rod 388 extending between the upper side frames. The operation of the control arm is governed in a manner to be hereinafter described, and when said control arm is moved into its 115 released position, as shown in Fig. 32, the clutch is thrown into action to connect the normally loose sleeve 381, carrying the several operating cams, to the continuously driven cam shaft 374 whereby the cycle of 120 operation of the mechanism is initiated. After the cycle of operation has been completed, the control arm 387 is moved into its stop position, as shown in Fig. 34, in which the rotating clutch lever 378 is brought into 125 engagement with the wedge cam 386 thereof and is thereby forced out of engagement with the clutch disk projections 376 whereby the clutch is disconnected and the several operating cams are brought to rest. In order 130

to overcome the inertia of the rotating clutch cam 378 when it is thus disengaged, a spring-pressed pin 389 is provided upon the control arm 387 against which the outer end 65 of the clutch lever 378 is brought to rest.

Having described the supporting frame of the lift alining, pressing and nailing mechanism 52 and the manner of operating the clutch by means of which power is connected to and disconnected from the several cams 380, 382, 383 and 384, the construction and operation of those parts which are controlled and actuated by said cams will now be set forth.

When the operator removes from the lift-assembling mechanism 50, a loosely assembled heel-pile that has just been built, it is placed in the heel receiving and holding device of the lift alining, pressing and nailing mechanism 52 with its breast resting upon the horizontally disposed breast plate 350, as shown in Fig. 35. Cooperating with the breast plate 350 are the pressure members 351 and 352 between which the component lifts of the heel are disposed and loosely supported in position. The pressure member 352 is stationarily and removably fixed to a boss 392 on the cap plate 368 and projects forwardly to permit its rounded forward end to engage the tread faced end of the heel. The relatively movable pressure member 351 is adjustably mounted by a pivot 393 upon one end of a supporting rod 394 so that it may accommodate itself to the angularity or inclination of the base-lift of the heel. The breast plate 350 is removably secured in position so that it may be replaced by other similar breast plates of different thicknesses and 40 inclinations or tapers to properly position heels of varying shapes and forms for the nailing operation. The relatively narrow forward end 369 of the cap plate 368 is provided with a trough 395 which surrounds the breast plate 350 and is intended to collect any excess of paste that may drip, or may be squeezed out from between the component lifts of the heel.

After placing the loosely assembled and 50 freshly pasted heel into the receiving and holding device where it rests upon its breast with its component lifts loosely assembled, or in loose order, as shown in Fig. 35, it is necessary to laterally shift the lifts while 55 thus loosely arranged to effect their alinement.

This is accomplished by means of the alining form comprising the pivotally mounted alining jaws 353, 354, 355, 356 and 60 357. Normally the alining jaws of the form occupy their open positions, as illustrated in Figs. 28 and 38, the upper jaw 353 being adapted to be brought into engagement with the upper or rear edges of the 65 lifts, the jaws 354 and 356 being disposed

on the left hand side of the heel and adapted to be brought into alining engagement with one side of the component lifts, and the jaws 355 and 357 being disposed on the opposite side of the heel to perform 70 similar functions.

The upper jaw 353 is pivoted upon a pin 398 (Fig. 32) to swing in a vertical plane and said pin is carried at the forward end of a bifurcated arm 399, the rear end of which is pivotally associated with a lug 400 that projects upwardly from the cap plate 368. The bifurcated arm 399 is provided with an upward projection 401 between which and the rear end of the cap plate, a 80 spring 402 is connected, for the purpose of maintaining a roll 403 (Fig. 35), carried on the extended pin 398, in operative position.

The several pairs of side alining jaws 354 and 356, and 355 and 357 are mounted to swing in horizontal planes, each pair of jaws being pivotally mounted upon a vertical pin 406 (Figs. 28 and 38) at the end of a horizontally disposed swinging supporting arm 405, said supporting arm being pivoted upon a stud 407 and being biased to its outermost position by means of a spring 408 that is attached between it and a point on the cap plate 368. The lower jaws 354 and 355 are also provided with outwardly extending arms 409 to the ends of which are attached springs 410 which serve to yieldingly urge them into their inward alining positions. The upper alining jaws 356 and 357, however, are merely 100 pivoted upon the pins 406 and are free to occupy any position they may assume.

The several jaws 353 to 357, inclusive, of the alining form are adapted to be actuated through the agency of a manually operable actuating lever 415 which assumes the position illustrated in Figs. 28 and 38 when the alining jaws are open. The actuating lever 415 (Figs. 28, 29, 30 and 32) is yoke shaped in form, having a plurality of arms 416, the lower ends of which are pivotally mounted upon a shaft 417 extending between the respective upper side frames, and the upper end of the lever is provided with a handle 418 by means of which it may be actuated. Between the relatively adjacent upper portions of the side arms 416 of the actuating lever 415, a member 419 (Figs. 30 and 39) carrying a roll 420, is mounted for vertical adjustment by means of a plurality of bolts 421, while an adjusting screw 422 is provided through the upper end of the actuating lever 415 which projects downwardly into engagement with the upper surface of the roll carrying member 419. By loosening the bolts 421 and adjusting the screw 422 in or out, the position of the member 419 and roll 420 may be varied as desired. The function of this roll is to engage a cam 130

surface 423 (Fig. 32) provided upon the upper alining jaw 353, and in conjunction with the engagement of a tail-piece 425 of the member 419 with the roll 403 carried 5 upon the pin 398, to actuate the upper alining jaw 353 into its preliminary alining and subsequent final clamping positions when the actuating lever 415 is manually brought forward by the operator. A 10 spring 426 interposed between the free end of the alining jaw 353 and the lever 415 serves to bias said jaw to its open position.

The several pairs of side alining jaws 354 and 356, and 355 and 357 are also actuated 15 by the forward movement of the actuating lever 415. For this purpose, each arm 416 of the actuating lever 415 is provided with an adjustably positioned member 430 (Figs. 27, 29 and 38) which carries a roll 431 upon 20 a pin 432 that extends downwardly from said member a material distance. Each of the roll carrying members 430 is provided with a laterally extending arm 433 having an angularly disposed slotted end 434, the 25 arm 433 being also provided with a slot 435. The arm 433 is seated in a notch 436 in the side arm 416 of the actuating lever and is secured thereto by means of a bolt 437 (Fig. 38) which projects through the slot 435 and 30 into the rear edge of the side arm 416. For purposes of lateral adjustment of the roll 431 and the pin 432, an adjusting bolt 439 is provided which projects through the slotted end 434 of the arm 433 and is 35 threaded into a boss 438 that projects laterally from the side arm 416.

When the manually operable actuating lever 415 occupies its released position, as shown in Figs. 26, 28 and 38, the downwardly extending ends of the pins 432 engage the arms 409 of the lower alining jaws 354 and 355 and hold said jaws in their open positions against the action of the springs 410.

As the actuating lever 415 is brought forward by the operator, the advance movement of the pins 432 permits the springs 410 to progressively swing the lower alining jaws 354 and 355 into engagement with the 50 lateral edges of the component lifts of the loosely assembled heel that rests in the receiving and holding device. The lower jaws, therefore, tend to yieldingly aline the lifts.

As the actuating lever 415 moves forward, the several rolls 431 that are mounted upon the pins 432 are brought into engagement 55 with cam surfaces 440 formed on the rear edges of the upper alining jaws 356 and 357, whereby said jaws are positively moved into their alining positions in engagement with the lateral edges of the loosely assembled lifts to effect their alinement.

Concurrently with this alining operation of the side alining jaws, the forward movement of the actuating lever 415 also actuates

the upper alining jaw 353 into alining position by reason of the engagement of the roll 420 with the cam surface 423 of said jaw in conjunction with the cooperation of the tail-piece 425 with the roll 403. The upper alining jaw 353, therefore, is forced downwardly into engagement with the upper or rear ends of the loosely assembled lifts to force their breast edges firmly against the breast plate 350. 75

An important feature of the invention resides in the peculiar operation of the alining jaws constituting the alining form, which are actuated in two stages or steps, in the first of which the upper jaw 353 and 80 two upper side jaws 356 and 357 are brought into predetermined alining positions, the angularity or inclination of which corresponds substantially to the slope or inclination 85 of the engaged portions of the heel while the component lifts thereof are loosely assembled, or in loose order. The desired angular positions of the jaws in their preliminary alining positions is secured by the use of jaws having properly designed cam 90 surfaces and by adjustment in the positions of the operating rolls 420 and 431, the jaws being replaced by other suitable ones to secure the requisite angularity, and the positions of the rolls being suitably adjusted 95 to accommodate heels of different sizes but of similar slopes or tapers.

In the second stage of operation of the alining form, the several jaws thereof are 100 permitted to be opened up slightly to a predetermined greater inclination or angularity which conforms to the slope or inclination of the heel after the lifts have been forced into the form and subjected to pressure to bring them into intimate contact, or into 105 close order, it being evident that the slope of a heel of closely assembled lifts is greater in angularity than that of the same heel while the lifts are loosely assembled. This change in the positions of the alining jaws, 110 however, is not effected until the heel is subjected to pressure, which is effected in the following manner.

Assuming the lifts to be preliminarily 115 alined in their loose order, as indicated in Fig. 35, the pressure member 351 is actuated to apply pressure thereto and clamp the lifts against the stationary pressure member 352. As already stated, the pressure member 351 is pivotally mounted upon the rod 120 394 so that it may accommodate itself to any pitch of heel. This rod 394 projects through an upwardly extending portion 445 (Fig. 32) of a plunger 446, and is secured thereto by suitable nuts 447. The plunger 125 446 is slidably mounted for back and forth motion in an opening provided in an enlarged portion 448 of the cap plate 368, and said plunger projects to the rear beyond said enlarged portion and carries a plurality 130

of rolls 449 and 450. The forward end of the plunger 446 is provided with a recess to receive a coiled spring 451 which is seated against the bottom of the recess and 5 against an upwardly projecting arm 452 that forms a part of the front plate 367. The spring 451 is relatively strong and normally urges the plunger 446, together with the movable pressure member 351, 10 rearwardly to cause said pressure member to force the preliminarily alined lifts into the form composed of the several alining jaws and to subject the heel to a predetermined yielding pressure, irrespective of its 15 height.

Prior to the application of pressure to the heel, the pressure member 351 is maintained in its open and inoperative position against the action of the spring 451 by means of a 20 bell crank 454 that is pivotally mounted upon a stud 455 carried by the side frames 365 and 366 and which acts upon the rear end of the plunger 446. The other arm of said bell crank carries a roll 456 that is 25 adapted to cooperatively engage the cam 382. This cam is designed to permit the pressure applying spring 451 to actuate the pressure member 351 at the proper time, and to subsequently release said pressure member 30 by causing the bell crank 454 to act upon the end of the plunger 446.

As the preliminarily alined heel is yieldingly forced into the form in the manner just described, the operating rolls 420 and 35 431 that cooperate with the respective cam surfaces 423 and 440 of the alining jaws 353, 356 and 357, pass over the points 458 and 459 of the respective cam surfaces, thereby permitting said jaws to open up to predetermined increased angularities or inclinations, which as hereinbefore stated, correspond to the exact pitch of the heel after it has been subjected to pressure. The alining jaws 353, 356 and 357 are thus firmly 45 held in their final alining and clamping positions, as shown in Figs. 29 and 32, to constitute a rigid form into which the preliminarily alined lifts are forced and subjected to pressure.

50 Although the lower alining jaws 354 and 355 are at first yieldingly actuated into their preliminary alining positions by the springs 410, the forward movement of the manually operable actuating lever 415 brings the extended lower ends of the pins 432 into positions spaced slightly behind said jaws. Said pins, therefore, serve as rigid restraints or stops for the jaws when the jaws are spread outwardly as the loosely 55 assembled and preliminarily alined lifts are subjected to pressure. Thus, all of the alining jaws of the form are rigidly held in their final alining and clamping positions 60 which are determined in advance to be such as to exactly conform to the heel after it has

been subjected to pressure. It is clear, therefore, that by reason of the two stage alining operation no disarrangements of the component lifts of the heel are possible and that a substantially perfectly alined heel is insured. 70

Although the initial forward movement of the actuating lever 415 is effected manually, the latter part of the operation is produced by the application of power. Moreover, this application of power to the actuating lever is not permitted until the several jaws of the alining form have been manually moved into substantially their preliminary alining positions, after which it is 80 impossible for the operator's fingers to remain in the machine where they may be injured. Furthermore, having once brought the actuating lever 415 forward to a position in which power is applied thereto, means 85 is provided for preventing the manual retraction thereof by the operator.

To effect these results, the actuating lever 415 is connected to the upper end of the clutch control arm 387 by means of a link 90 460 (Figs. 26 and 32). When the actuating lever occupies its inoperative position, as shown in Figs. 26 and 34, the control arm 387 is maintained in such position as to prevent the clutch lever 378 from being thrown 95 into engagement with the clutch disk 375, whereby the application of power is prevented. When, however, the actuating lever has been manually brought forward to an extent sufficient to place the jaws of the alining form in substantially their preliminary 100 alining positions, the control arm 387 is withdrawn and the clutch lever 378 released and permitted to effect an operative driving engagement with the continuously operating clutch disk 375 whereby all of the cams 380, 382, 383 and 384 are connected to the source 105 of power.

Just prior to the throwing in of the clutch to effect the power operation of the machine, 110 a roll 463 (Figs. 28 and 37) that is carried at the end of a lever 464 is dropped in a cam path 465 in the cam 384, as indicated in dot and dash lines in Fig. 37. The lever 464 is pivotally mounted upon a stud 466 115 projecting inwardly from the left hand side of the cap plate 368, and its other end is connected by means of a link 467, having bifurcated ends, with an arm 468 forming an integral part of the manually operable 120 actuating lever 415. The cam 384 is provided with a spring-pressed latch 469 adjacent the opening through which the roll 463 is dropped into the cam path 465, so that as soon as the roll has passed the yielding 125 latch 469, it serves as a lock to prevent the removal of the roll therefrom, and at the same time to restrain the actuating lever 415 against manual retraction.

Having thus locked the manually operable 130

actuating lever 415 in the manner just described, and having connected the machine to the source of power, the several cams are started into operation. Immediately thereafter the cam 384 operates upon the roll 463 to force the actuating lever 415 to its foremost position and to release the several alining jaws from their preliminary alining positions. Subsequently the cam 382 (Fig. 32) releases the pressure-applying spring 451 and the pressure member 351 is actuated to force the heel into the alining jaws in their final alining and clamping positions and to subject the heel to a predetermined yielding pressure.

An additional and positive pressure is then applied to the heel in the form, after which the pressure member 351 is positively restrained to provide a rigid and firm backing against which the nailing mechanism may operate. To this end an eccentric wedge cam 472 (Fig. 32) is rotatably mounted upon a stud 473 and is acted upon by a spring 474 that is attached through an adjustable tension device 475 to the upper end of a supporting arm 476 which projects upwardly from the cap plate 368. An arm 477 forms a part of a bell crank with the wedge cam 472, and carries at its end a roll 478 that is adapted to cooperate with the cam 380 on the cam shaft 374. The wedge cam 472 in its operative position, as shown in Fig. 32, cooperatively engages the roll 449 that is fixed to the side of the plunger 446 to which the pressure member 351 is attached. The spring 474 is preferably heavy relative to the pressure-applying spring 451, and the tension thereof is adjustable by means of the tensioning device 475.

The cam 380 is designed and angularly positioned upon the cam shaft so that after a predetermined yielding pressure has been exerted upon the heel through the spring 451, the roll 478 on the wedge cam bell crank is disengaged from the cam 380, thereby permitting the relatively heavy spring 474 to pull the wedge cam 472 upwardly against the roll 449. By reason of the strength of the spring and the eccentric form of the wedge cam, said cam is caused to force the plunger 446, together with the pressure member 351, toward the right to exert an additional and positive pressure upon the heel. The amount of positive pressure to which the heel is thus subjected depends entirely upon the strength of the spring 474 and, therefore, any degree of pressure may be obtained in accordance with the adjustments of the spring tensioning device 475.

With this construction it is clear that the heel, regardless of its height, is first subjected to a predetermined and substantially uniform yielding pressure that is effected by the spring 451, and thereafter, the heel is

subjected to an additional predetermined amount of positive pressure through the action of the wedge cam 472. The wedge cam 472 serves a double function, since it also positively locks the pressure member 351 in its final pressure-applying position so that it is positively held and constitutes a rigid backing against which the nail is driven in a manner to be later described.

The next operation is to nail together the alined and pressed heel, and this is accomplished by the nailing device comprising the nail driver 358 (Figs. 31 and 32). The nail driver 358 is horizontally disposed and projects slidably through an opening in the rear pressure member 352 which is provided with a V shaped groove 480, to which the nails are automatically supplied by the feed tube 360 and in which the nails lie in substantially horizontal position. The nail driver 358 is held by a suitable chuck 481 that is mounted upon the end of a plunger 482 that is adapted to reciprocate in an opening in a longitudinal boss 483 that forms an integral part of the cap plate 368. The rear end of the plunger 482 is provided with an adjustable end member 484 (Figs. 28 and 32) having a vertically disposed channel or groove to receive an engaging member 485 that is secured at the upper end of a bell crank 486. The end member 484 is also provided with a socket 487 to receive one end of a spring 488 that is held in a recess 490 in the boss 483 (Figs. 32 and 34). The spring 488, therefore, serves to urge the nail driver 358 rearwardly and to maintain it in its retracted inoperative position and, at the same time, to hold a roll 492 that is carried at the other end of the bell crank 486 in engagement with the cam 383 on the cam shaft 374. The cam 383 controls the operation of the nail driver 358 and is designed to positively advance the nail driver 358 to drive a nail through the component lifts of the heel after the heel has been subjected to pressure and firmly clamped in position. The nail is driven through the heel in the direction of its height and against the rigid backing provided by the positively locked pressure member 351 which serves to turn over or clench the point of the nail when it is engaged thereby, as shown in Fig. 32.

Among the important features of the invention is the construction and arrangement of the nail driving device with respect to the means for holding and clamping the freshly pasted heel in position to be nailed. This arrangement is such that the freshly pasted heel is placed on its breast upon the breast plate 350 and the nail driver is located adjacent and to the rear thereof and operates in a horizontal plane during its nailing operation. Thus, the heel receiving and holding means and the nail driving de-

vice are disposed side by side so that any excess of paste that may be carried by the freshly pasted heel or may be squeezed out from between its lifts, cannot possibly come 5 in contact with the nailing apparatus, which always remains clean and free from paste and operates with reliability and effectiveness. Moreover, this arrangement also permits of the use of an automatic nail supplying 10 mechanism which it is impossible to employ, in a position in which it may be gummed by contact with paste.

Before describing the construction and operation of the automatic nail supplying 15 mechanism, however, another advantageous feature of this horizontal side by side arrangement should be considered. With this arrangement, the nail receiving groove 480 is horizontally disposed and, therefore, as 20 the nails are supplied thereto prior to the nail driving operations, said nails gravitate to and always occupy similar positions resting at one end upon their heads and at the other upon their pointed ends. This position 25 is substantially horizontal, although slightly inclined thereto by reason of the somewhat enlarged diameter of the head of the nail. Each nail, however, occupies the same position and, therefore, must be driven 30 into the heel in substantially definite and fixed position, it being well known in the art that nails are driven along lines in the direction in which they are positioned when the driving operation takes place.

35 Advantage is taken of this fact, in order to insure the proper positioning of the securing nails in the heels, and particularly in relatively high heel-piles from which high Louis heels are to be made. In some forms 40 of Louis heels the breasts of which are to be greatly undercut and which slope forwardly at quite extreme angles, the areas of cross sections of the heels at certain points are extremely small, which makes it necessary to 45 carefully locate the nails which secure together the component lifts so that they shall not protrude beyond the limits of the heels in their final forms.

To adapt the alining, pressing and nailing 50 mechanism of the present invention to operate upon heels of different styles and forms and to properly position the securing 55 nails therein in accordance with the peculiar characteristics of the heel being operated upon, the heel receiving and holding device comprising the breast plate 350 and the relatively movable pressure members 351 and 352 are made adjustable. Fig. 33 illustrates 60 said receiving and holding device adjusted to properly position and hold a heel-pile from which a high Louis heel is to be produced, the final shape of the heel being indicated in dotted lines. In this construction, the breast plate 350 is tapering and 65 inclined in form; the adjustable pressure

member 351 is tilted upon its pivot to accommodate the inclination of the base-lift of the heel; while the rounded end of the stationary pressure member 352 permits the heel to be properly positioned with respect 70 thereto. The taper and thickness of the breast plate 350 is suitably chosen with respect to the particular characteristics of the heel to be built in order to properly position it so that the nail, which is always driven 75 in a predetermined direction dependent upon its definite position in the nail receiving groove 480, is driven through the restricted area of the heel and in such position that it will not be exposed when the 80 heel breast is undercut and the lateral surface trimmed to its final shape.

Referring again to Fig. 32, after the nail has been driven by the nail driver 358, the cam 384 (Figs. 28 and 37) operates through 85 its cam surface 496 to force the cam roll 463 outwardly and, through the connections already described, to positively throw back the actuating lever 415 of the alining form into its normal retracted position, as shown in 90 Figs. 26, 37 and 38. This operation releases the several alining and clamping jaws 353 to 357, inclusive, as will be understood.

At substantially the same time, the cam 380 (Figs. 28 and 32) is brought into position to engage the roll 478 whereby the wedge cam 472 is withdrawn from its operative position to release the plunger 446 carrying the pressure member 351. Subsequently, the cam 382 operates upon the roll 100 456 to cause the bell crank lever 454 to force the plunger 446 and its pressure member 351 forwardly against the action of the spring 451 whereby the pressure is relieved from 105 the heel and the heel receiving and holding device is restored to its initial open position.

Immediately after the pressure member 351 has been retracted to its open position, the cam 383, by reason of a raised portion 110 498 (Fig. 32) thereof, cooperates with the roll 492 and bell crank 486 to give the nail driver 358 a slight projection forwardly to loosen the heel that may possibly have adhered to the breast plate 350. The nail 115 driver is then immediately retracted slightly to its initial position, at which time the alining, pressing and nailing mechanism is brought to rest by automatically disengaging the clutch lever 378 from the continuously rotating clutch disk 375. This is accomplished through the agency of the cam 386 on the control arm 387 which has, in the meantime, been placed in its operative stop position by the automatic retraction 120 of the main actuating lever 415, in which position it engages and throws out the rotating clutch arm 378 when it reaches a position in which the engagement may take 125 place, as shown in Fig. 34.

As already stated, the horizontal and side by side relation of the heel receiving and holding device and the nail driving device permits the employment of an automatic nail supplying mechanism. This mechanism is adapted to supply a nail to the nail receiving groove 480 at each cycle of operation of the machine. The nail supplying mechanism comprises the nail holder 359 and the feed tube 360 which delivers the nails to the receiving groove 480, and said nail holder 359 is conveniently mounted above the machine upon a bracket 500 (Figs. 1, 2, 26, 40, 41 and 42) which is secured to the cap plate 368. The upper portion of the bracket 500 carries a fixed pin 501 that projects upwardly therefrom to receive a rotatable supporting spider 502 that is yieldingly held in position upon a portion of the bracket 500 and which is provided with a plurality of radial arms 503 that are joined by means of segmental members 504. At the extremities of the arms 503, a plurality of upwardly projecting pins 505 are located, and these pins 505 are adapted to support the nail holder 359 which comprises an annular member 506 having a plurality of inwardly extending apertured lugs 507 which set over the pins 505 and by means of which the annular member 506 is removably supported in position. The nails are held in both the inner and the outer corrugations of a corrugated strip of sheet material 508 that is secured to the periphery of the annular member 506, and in order to retain the nails in the outer corrugations of said strip, a plurality of bands 509 are positioned around the periphery of the corrugated strip and in contact therewith. To support the nails, a supporting ring or plate 510 is disposed immediately beneath the annular member 506 and is loosely supported in position by means of washers 511 that are held upon screws 512 which are threaded into inwardly projecting lugs 513 that are formed integrally with the annular member 506.

This structure is such that the annular member 506 may be removed from the pins 505 and, through the agency of the supporting washers 511, carries the supporting ring 510 with it. The supporting ring 510 is provided with an aperture 514 that is located beneath the corrugations of the nail holder in such position that as the holder is advanced in steps, the nails contained therein are progressively brought over the aperture 514 whereby said nails are permitted to drop through and into the flexible feed tube 360 which is supported by the bracket 500 in a position directly beneath said aperture. During the normal operation of the nail supplying mechanism, the supporting ring 510 is restrained against rotative movement by means of a fixed pin 516 that projects

into an opening in said ring when it is properly positioned.

The nail holder 359 is adapted to be advanced, one step at a time, at each cycle of operation of the alining, pressing and nailing mechanism, and its feeding movement is effected by means of a spring-pressed pawl 517 that is pivotally mounted upon a pin 518 at the upper end of an arm 519 which forms a part of a bell crank pivotally mounted upon the bracket 500 by means of a pin 520. The bell crank also comprises an arm 521 that carries at its outer end a roll 522 which cooperatively engages a cam path 523 that is provided in a cam 524. The cam 524 is fixed to a shaft 525 journaled in the bracket that carries a sprocket 526 which is connected by means of a chain 527 (Figs. 1 and 2) to a sprocket 528 that is fixed by means of a set screw 529 (Fig. 34) to the sleeve 381 surrounding the cam shaft 374 and upon which the several operating cams of the lift alining, pressing and nailing mechanism are mounted.

Inasmuch as the nail holder 359 is advanced in steps by reason of the engagement of the pawl 517 with each outer corrugation of the corrugated member 508, and inasmuch as nails are contained in both the outer as well as the inner corrugations of said member, it is necessary to make provision for advancing the nail holder, a half corrugation at each step. To effect this result, the ratio of the sprockets 526 and 528 is so chosen that for each complete cycle of the alining, pressing and nailing mechanism, the cam 524 is rotated a half revolution; which by reason of its design, causes the pawl 517 to advance the nail holder 359 a step corresponding to one half of a corrugation. During the next succeeding cycle of operation of the alining, pressing and nailing mechanism, the cam 524 completes the other half of its revolution during which it advances the nail holder 359 another half corrugation. The pawl is then retracted to engage the next succeeding corrugation. In this manner, the nail holder 359 is advanced in steps, a half corrugation at a time for each cycle of operations of the alining, pressing and nailing mechanism, whereby the nails contained in the inner and outer corrugations of the corrugated strip 508 are progressively positioned over the aperture 514 and feed tube 360 and are supplied one at a time through the tube 360 to the nail receiving groove 480 in position to be acted upon by the nail driver 358.

When the nail holder 359 has been emptied, the annular member 506, together with the supporting ring 510, may be removed bodily for reloading. To facilitate the removal of the nail holder, a manually operated detent or latch 530 is provided

which is pivoted upon a pin 531 and may be swung into position to engage the pawl 517 and positively hold it in inoperative position to permit the nail holder 359 to be raised from the supporting pins 505 and removed. To prevent relative rotative movement between the annular member 506 and the supporting ring 510 carried thereby upon the washers 511, said annular member 506 is provided with a spring-pressed pin 533 (Fig. 36) that, when the holder is removed, is adapted to be projected into the opening in the ring 510 that receives the fixed pin 516 when the holder is in position. 10 This construction insures that no nails are lost through the feeding aperture 514 after the nail holder has been loaded.

When the nail holder 359 is again placed in operative position, upon the pins 505, 20 the pin 516 projects into the opening in the supporting ring 510 and by reason thereof, pushes out the spring-pressed pin 533, whereby the supporting ring 510 is held stationary in position, while the annular 25 member 506 resting upon the spider 502 is permitted to be stepped along in the manner already described to successively deliver the nails into the feed tube 360.

Having described the construction and operation of the lift-assembling mechanism 50 and the lift alining, pressing and nailing mechanism 52, the interconnecting mechanism, by means of which they are controlled as a unit will now be set forth.

35 While these two mechanisms may be controlled and operated independently, as already described, under normal conditions the operation of the lift-assembling mechanism 50 is governed by and dependent upon 40 the operation of the lift alining, pressing and nailing mechanism 52. For this purpose, the control arm 387 (Fig. 26) of the alining, pressing and nailing mechanism 52 is provided with an integral arm 540 having 45 a universal connection 541 with a vertical rod 542, the lower end of which is attached to an arm of a bell crank 543 (Fig. 1), the other arm of which is pivotally connected to the left hand end of a control rod 544 (Figs. 1, 7 and 26) that extends longitudinally of the machine. The right end of the control rod is provided with a latch 545 which normally rests upon a pin 547 carried at the lower end of a control arm 548, as 55 shown in Figs. 1 and 7. The control arm 548 is fixed to the transverse rod 106 to which is secured the wedge cam member 105 that, in conjunction with the interconnected wedge cam member 96, controls the operation 60 of the clutch lever 92 and thereby of the main clutch of the lift-assembling mechanism 50. Although the clutch may be controlled by the handle 98, through the agency of the wedge cam members 96 and 105 in 65 the manner already described, it is evident

that the clutch may also be governed by means of the control arm 548 which is adapted to be actuated by means of the control rod 544 from its inoperative position, shown in full lines, to its operative position, shown 70 in dot and dash lines, in Fig. 7.

This control rod 544 is mechanically associated with the main actuating lever 415 of the lift alining, pressing and nailing mechanism 52 in the manner just described 75 and the connections referred to are so constructed and arranged that the supply of power to said mechanism must be effected before the latch 545 on the end of the control rod 544 moves the control arm 548 a 80 sufficient distance to cause the operation of the clutch of the lift assembling mechanism 50. Hence, power is supplied to the lift alining, pressing and nailing mechanism 52 before the application of power to the lift- 85 assembling mechanism 50 is effected, so that the alining, pressing and nailing mechanism completes its cycle of operation and the actuating lever 415 thereof is thrown back into its initial position prior to the completion 90 of the cycle of operation of the lift-assembling mechanism. When the actuating lever 415 is restored to its initial inoperative position, as shown in Fig. 26, the control rod 544 with its latch 545 is also returned to 95 its normal position, as indicated in Figs. 1 and 7, by reason of the connections already described. Therefore, when the lift assembling mechanism 50 has completed its cycle 100 of operation and the clutch latch 111 has been automatically released by one of the cam lugs 114, the spring 101 may restore the wedge cam members 96 and 105 to their stop positions and at the same time return the control arm 548 to its initial stop position, 105 as shown in Fig. 7. The operation of the lift assembling mechanism 50, therefore, is dependent upon and governed by the lift alining, pressing and nailing mechanism 52, so that both component mechanisms of the 110 heel building machine comprising the present invention are controlled as a unit.

As already stated, these two mechanisms may be governed independently so that either machine may be operated singly if 115 desired. To accomplish this result, it is necessary to make provision for temporarily interrupting the interconnecting mechanism through the agency of which the machines are controlled as a unit, and this is effected by means of a treadle 550 (Fig. 1) which is pivoted upon the pedestal 70 and is normally held by means of a spring 551 in such position that a pin 552 carried at its upper end lies beneath the control rod 544. By 120 stepping on the treadle 550, the pin 552 is raised into engagement with the control rod 544 whereby said rod, and the latch 545 attached thereto, is elevated out of operative 125 engagement with the pin 547 on the control 130

arm 548. Thus, the control rod 544 and the control arm 548 are free to move independently, so that both the lift alining, pressing and nailing mechanism 52 and the lift-
5 assembling mechanism 50 may be operated singly and independently, if the occasion requires.

In the foregoing description, and in the following claims, an unpasted "base-lift" 10 has been referred to. It will be recognized by those skilled in the art that the component heel lift to remain unpasted may be at either the heel-seat or the tread end of the heel depending upon two heel building factors, namely, whether the heel pile rests upon the receiver in normal or inverted position, and whether the paste is applied to the upper or the lower faces of the lifts being assembled. Accordingly "base-lift" is 15 used as descriptive of the lift at either end of the heel unless the accompanying text defines its exact relation to the other component lifts of the heel.

In the following claims a definition will 25 be found of the heel building mechanism as an independent machine, and of the combined mechanisms comprising the lift assembling devices, the lift alining, pressing and nailing devices in part or in whole, and 30 the inter-control mechanism. Claims to the lift alining, pressing and nailing devices, separately or in combination, will be found in a divisional application, Ser. No. 410,444, filed September 15, 1920.

Having described the construction and 35 operation of the preferred form of the present invention, that which is claimed as new is:

1. A heel building machine having, in 40 combination, a plurality of lift magazines, means for producing therefrom a series of lifts in a row, means for operating upon the lifts, and an endless conveyer for conveying the lifts so produced in succession to 45 said operating means.

2. A heel building machine having, in 50 combination, a plurality of lift magazines, means for producing therefrom a series of lifts in a row, a pasting device, and an endless conveyer for advancing the lifts in succession to said pasting device.

3. A heel building machine having, in 55 combination, a plurality of lift magazines, means for producing therefrom a series of lifts in a row, and an endless conveyer for delivering said row of lifts serially to an operating station by a single continuous movement of the conveyer.

4. A heel building machine having, in 60 combination, means for producing a series of lifts, a receiving device, and continuously operated means for advancing the lifts in succession to said receiving device.

5. A heel building machine having, in 65 combination, means for producing a series

of lifts, and means operating continuously in one direction for conveying away the lifts so produced.

6. A heel building machine having, in combination, a plurality of lift magazines, 70 means for producing a series of lifts from said magazines, a device for acting upon the lifts, and a continuously operated conveyer for advancing the lifts in succession to said device. 75

7. A heel building machine having, in combination, a plurality of lift magazines, means for producing a series of lifts from said magazines, a pasting device for applying paste to one surface of each lift, and 80 means for advancing said lifts serially past said pasting device having a continuous movement in one direction during said advance.

8. A heel building machine having, in 85 combination, a plurality of lift magazines, means for producing a series of lifts from said magazines, a pasting device, a receiving device, and continuously operated means for advancing the lifts serially past the pasting 90 device and delivering them in a pile into said receiving device.

9. A heel building machine having, in combination, a plurality of lift magazines, 95 means for producing a series of lifts from said magazines, a belt conveyer disposed parallel to the magazines for conveying away the lifts so produced and means for operating said belt continuously in one direction while the lifts are being conveyed 100 away.

10. A heel building machine having, in combination, a continuously operated conveyer, a series of lift magazines, means for producing a series of lifts from the magazines and depositing them upon said conveyer, manually controllable means for starting the operation of said producing means, and automatic means for discontinuing the operation thereof at the end of a 105 single cycle.

11. A heel building machine having, in combination, a row of lift magazines, means for producing a row of lifts from said magazines, a pasting device, a continuously moving conveyer for advancing the row of lifts serially to said pasting device, and means for manually controlling the starting of the cycle of operations of said producing means and for automatically discontinuing the operation thereof at the end of the cycle. 115

12. A heel building machine having, in combination, a pasting device, continuously operated means for feeding a succession of lifts past said pasting device and assembling them in a pile, and manually controllable means for producing a row of lifts and depositing them in position to be advanced by said continuously operated feeding means. 125

13. A heel building machine having, in 130

- combination, a continuously moving conveyer, means for producing a series of lifts and depositing them in dispersed relation upon the conveyer, and means for temporarily arresting the movement of the lifts so deposited. 70
14. A heel building machine having, in combination, a continuously moving conveyer, means for producing a series of lifts and depositing them in a row upon the conveyer, and a plurality of fingers periodically positioned over the moving conveyer for temporarily restraining the several lifts of the row deposited thereon. 75
15. A heel building machine having, in combination, a continuously moving conveyer, means for producing a series of lifts and depositing them upon the conveyer with their breast edges in advance, and means 80
- 20 acting temporarily upon the breast edges of the several lifts for effecting their alinement upon the conveyer. 85
16. A heel building machine having, in combination, a continuously moving conveyer, means for producing a series of lifts and depositing them upon the conveyer, and means acting temporarily upon the several lifts deposited upon the conveyer for causing the breast edges thereof to occupy corresponding positions. 90
17. A heel building machine having, in combination, a continuously moving conveyer, means for producing a series of lifts and depositing them upon the conveyer, a plurality of fingers normally positioned over the moving conveyer for temporarily restraining the several lifts of the row deposited thereon, and means acting subsequently to the deposition of lifts upon the 95
- 40 conveyer for withdrawing the fingers to permit the transfer of the lifts by the moving conveyer. 100
18. A heel building machine having, in combination, a continuously moving conveyer, means for producing a series of lifts and depositing them in a row upon the conveyer with their breast edges in advance, a plurality of pivotally mounted fingers normally disposed immediately above the conveyer and extending transversely across it, said fingers being arranged to engage the breast edges of the several lifts during the continued operation of the conveyer to restrain the movement of said lifts and effect 110
- 50 their alinement, and means acting subsequent to the production and deposition of the lifts upon the conveyer for concurrently raising the fingers to permit the advancement of the lifts by the conveyer. 115
- 60 19. A heel building machine having, in combination, a continuously moving conveyer, means for producing a series of lifts and depositing them in a row upon the conveyer, means for temporarily arresting the 120
- 65 movement of and alining the lifts upon the 125
- conveyer, a pasting device to which the lifts are delivered by the conveyer in succession after the release of the lifts, and means upon which the alined and pasted lifts are deposited in a pile. 130
20. A heel building machine having, in combination, a travelling conveyer having an uninterrupted plane surface extending substantially the length of the machine, a plurality of lift magazines disposed in a row parallel to the conveyer and independently adjustable in position throughout the length of the conveyer, and means operative to produce a series of lifts from the magazines irrespective of their positions and to deposit said lifts in a row upon the uninterrupted plane surface of said conveyer. 80
21. A heel building machine having, in combination, a travelling belt conveyer having an uninterrupted plane surface extending substantially the length of the machine, a series of lift magazines comprising a plurality of partitions adjustable in position along the length of the conveyer and between which the lifts are stacked, and means operative upon the lifts in the magazines irrespective of their positions for producing a series of lifts therefrom and depositing them in a row upon the uninterrupted surface of said conveyer. 95
22. A heel building machine having, in combination, a continuously moving conveyer, means for producing a series of lifts and depositing them upon the conveyer, and means cooperating with each lift so produced for insuring an accurate delivery of the lifts in predetermined positions to the moving conveyer. 100
23. A heel building machine having, in combination, a continuously moving conveyer, means for producing a series of lifts and depositing them upon the conveyer, and means cooperating with each lift so produced for maintaining said lifts above and out of engagement with the moving conveyer until substantially the whole of each lift overhangs the conveyer and for then permitting the lifts to drop freely upon the conveyer without disturbing the relative alinement of the lifts. 105
24. A heel building machine having, in combination, a continuously moving conveyer, means for producing a series of lifts and depositing them upon the conveyer, and a plurality of spring-pressed devices cooperating with each lift so produced for maintaining them out of contact with the moving conveyer until substantially the whole of each lift overhangs the conveyer and then permitting them to be deposited without change of position upon the conveyer. 115
25. A heel building machine having, in combination, a supporting plate, a row of lift magazines, a continuously moving con- 120

veyer disposed parallel to the row of magazines and slightly below the supporting plate, means for advancing the lowermost lifts of the magazines across the supporting plate and depositing them upon the conveyer, and means cooperating with each of the lifts so advanced for maintaining the lifts in the plane of the supporting plate until substantially the whole of each of the lifts overhangs the conveyer and thereafter permitting the lifts to drop upon the conveyer.

26. A heel building machine having, in combination, a movable lift carrier, means for producing a series of lifts and depositing them in a row upon the carrier, a pasting device, and means for actuating the carrier to deliver the lifts in succession to the pasting device.

27. A heel building machine having, in combination, a movable lift carrier, means for producing a series of lifts and depositing them in a row upon the carrier, a pasting device, and means for causing the carrier to advance the lifts concurrently towards the pasting device and deliver them thereto in succession.

28. A heel building machine having, in combination, a movable lift carrier, means for producing a series of lifts and depositing them in a row upon the carrier, a pasting device, and means for imparting to the carrier a movement sufficient to deliver all of the lifts in succession to the pasting device.

29. A heel building machine having, in combination, a movable lift carrier, means for producing a series of lifts and depositing them in a row upon the carrier, and means cooperating with the carrier for collecting the lifts in a pile.

30. A heel building machine having, in combination, a series of lift magazines, a movable carrier, means for producing lifts from the magazines and depositing them in a row upon the carrier, and means to which the lifts comprising said row are delivered by the carrier in succession one upon another to form a heel.

31. A heel building machine having, in combination, a row of lift magazines, a movable belt conveyer disposed adjacent and parallel to the row of magazines, means for periodically producing from the magazines a series of lifts and depositing each series in a row upon the belt conveyer and means for advancing the conveyer a distance at least equal to the length of the row intermediate each deposit of lifts.

32. A heel building machine having, in combination, a row of lift magazines, a traveling conveyer having an uninterrupted plane surface, and means for producing a series of lifts from said magazines and de-

positing them upon said uninterrupted plane surface of said conveyer in dispersed relation.

33. A heel building machine having, in combination, a row of lift magazines, a conveyer movable in a single direction past said magazines, means for producing a series of lifts sufficient for a single heel from said magazines and depositing them in a row within the control of said conveyer, and means to which the lifts are delivered successively by said conveyer one upon another.

34. A heel building machine having, in combination, a row of lift magazines, means for producing a row of lifts, a traveling endless conveyer upon which the row of lifts is deposited, and a pasting device to which the lifts are delivered in succession by said conveyer.

35. A heel building machine having, in combination, a movable lift carrier, means for producing a series of lifts and depositing them in a row upon said carrier, a receiving device, and means for actuating said carrier in a single movement to feed the row of lifts in serial relation and stack them one by one in said receiving device.

36. A heel building machine having, in combination, a movable lift carrier, means for producing a series of lifts and depositing them in a row within the control of said carrier, a receiving device, and means for actuating the carrier in a single movement a distance at least equal to the length of the row of lifts for feeding the lifts concurrently, while in serial relation to said device by which they are received one upon another in heel form.

37. A heel building machine having, in combination, means for producing a series of lifts, a paste pot and roll removable as a unit from the machine, and means for feeding the lifts so produced in succession over the paste roll.

38. A heel building machine having, in combination, a paste pot and roll removable as a unit from the machine, means for producing a series of lifts and advancing them in succession over the paste roll, and manually operable means for locking the removable paste pot and roll in position.

39. A heel building machine having, in combination, means for producing a series of lifts and depositing them in dispersed relation, a conveyer for serially advancing the lifts so produced, a unit comprising a paste pot and roll disposed at one end of the conveyer, and means for feeding the lifts advanced by the conveyor in succession over the paste pot and in contact with paste roll.

40. A heel building machine having, in combination, a paste pot and roll, a set of feed wheels disposed above said paste pot for advancing lifts across said roll, and

- means for producing a series of lifts and advancing them serially into control of said feed wheels. 65
41. A heel building machine having, in combination, means for producing a series of lifts in a row, a receiving device, and means acting in succession upon the lifts of said series for advancing and delivering them serially in stack formation to the receiving device. 10
42. A heel building machine having, in combination, means for producing a series of lifts, a receiving device, and a plurality of separate feeding means acting successively upon the lifts so produced for advancing the lifts and delivering them to the receiving device. 75
43. A heel building machine having, in combination, means for producing a series of lifts, a receiving device, and a movable conveyer and a set of feed wheels for acting successively upon the lifts so produced for delivering them in a pile into the receiving device. 20
44. A heel building machine having, in combination, means for producing a series of lifts, a receiving device, a movable conveyer upon which the lifts so produced are deposited, and a set of feed wheels acting upon the upper surfaces of the lifts for delivering the lifts into the receiving device. 30
45. A heel building machine having, in combination, means for producing a series of lifts, a receiving device, a movable conveyer upon which the lifts so produced are deposited for serially feeding the lifts, and other means disposed at the end of the conveyer and acting upon the successive lifts while still upon the conveyer for delivering the lifts in a pile into said receiving device. 40
46. A heel building machine having, in combination, means for producing a series of lifts, a receiving device, a movable conveyer upon which the lifts so produced are deposited, a supporting member disposed at the end of the conveyer and in the plan thereof, and means disposed above said supporting member and taking control of the lifts while still upon the conveyer for delivering the lifts in a pile into the receiving device. 50
47. A heel building machine having, in combination, means for producing a series of lifts, a movable lift carrier for serially advancing the lifts so produced, and a plurality of independent yieldingly mounted rotatable feed wheels for acting upon the successive lifts advanced by the heel carrier and effecting their further advancement. 55
48. A heel building machine having, in combination, means for producing a series of lifts, means acting upon the lower surfaces of the lifts for effecting their advancement, and means acting upon the upper surfaces of the lifts for subsequently effecting further advancement thereof. 65
49. A heel building machine having, in combination, means for producing a series of lifts, means for concurrently advancing the lifts, and means for subsequently acting upon the lifts in succession for effecting their further advancement. 70
50. A heel building machine having, in combination, means for producing a series of lifts, and a plurality of means acting successively upon the lifts for effecting their advancement, the second means taking control of the successive lifts before the first means relinquishes control of them. 75
51. A heel building machine having, in combination, a paste roll, a set of continuously operated feed wheels disposed above the paste roll, and means for producing a series of lifts and delivering them in rapid succession to the feed wheels. 80
52. A heel building machine having, in combination, a paste roll, means for producing a series of lifts and advancing the lifts in rapid succession to a point adjacent the paste roll, and a plurality of feed wheels for acting upon the lifts as they are advanced and feeding them across the paste roll. 90
53. A heel building machine having, in combination, a paste roll, means for producing a series of lifts and advancing the lifts in rapid succession to a point adjacent the paste roll, and a plurality of feed wheels for engaging and taking control of the successive lifts as they are advanced and feeding them across the paste roll while preventing their disarrangement of position during such feeding movement. 95
54. A heel building machine having, in combination, a row of lift magazines, means for producing a series of lifts from the magazines and depositing them in a row, a conveyer for feeding the lifts so produced in the line of the row, and a pasting device disposed at one end of the conveyer and embodying a paste roll and a set of feed wheels for acting upon the successive lifts fed by the conveyer and feeding them in rapid succession over the paste roll. 100
55. A heel building machine having, in combination, means for producing a series of lifts, a paste roll, and means acting concurrently upon the lifts and subsequently acting upon the lifts in succession for feeding the lifts past said paste roll. 115
56. A heel building machine having, in combination, means for producing a series of lifts, a paste roll, and means including a series of continuously operated and independently mounted feed wheels for feeding said lifts in succession over said paste roll. 120
57. In a heel building machine, the combination of means for producing a series of lifts in alinement, means for pasting the

- lifts of said series, means for producing a single dry lift out of alinement with said series and means for assembling all of the lifts into a pile.
58. In a heel building machine, the combination of means for producing a series of lifts in a single plane, means for pasting the lifts of said series, means for producing a single dry lift in another plane, and 10 means for assembling all of the lifts into a pile.
59. In a heel building machine, the combination of lift receiving means, means for producing a series of lifts in a single plane, 15 means for pasting the lifts of said series, means for producing a single dry lift in another plane, and means for assembling all of the lifts in the receiving means to form a pile with a face of the dry lift outermost.
- 20 60. In a heel building machine, the combination of lift receiving means, means for producing a series of lifts in a single plane, means for pasting the lifts of said series, and means for producing a single dry lift in another plane and for delivering to the receiving means first the dry lift and then the 25 series of pasted lifts to form a complete pile with a dry outer face.
- 30 61. In a heel building machine, the combination of a lift receiving means, means for producing a series of lifts in a single plane, means for pasting the lower faces of the lifts of said series, and means for producing a single dry lift in another plane and for delivering to the receiving means first the dry 35 lift and then the pasted lifts to produce a pile having dry outer faces.
- 40 62. A heel building machine having, in combination, means for producing a lift and delivering it in dry condition to an assembling station, means for producing a series of other lifts, and means for successively applying paste thereto and delivering them in succession and in superposed relation upon 45 said dry lift.
- 50 63. A heel building machine having, in combination, a receiving device, means for producing and delivering a lift in dry condition into said receiving device, means for producing a series of other lifts and delivering them in a pile upon the dry lift through 55 a path different from that traversed by the dry lift, and means in the path traversed by said series of lifts for applying paste thereto.
- 60 64. A heel building machine having, in combination, a plurality of lift magazines, means for producing a series of lifts therefrom, a pasting device disposed intermediate one of the lifts and the others so produced, and means for advancing said other lifts past said pasting device and delivering them in a pile upon the first lift.
- 65 65. A heel building machine having, in combination, a plurality of lift magazines, a receiving device, means for producing a row of lifts from said magazines, one of the lifts being delivered into said receiving device, a pasting device disposed in the line of said row of lifts and between the lift in said receiving device and the other lifts, and means for advancing said other lifts of the row in succession past the pasting device and delivering them in a pile upon the lift in said receiving device. 70
66. A heel building machine having, in combination, a row of lift magazines, means for producing a series of lifts therefrom, a pasting device, a receiving device, means for advancing said series of lifts in succession past said pasting device and delivering them into said receiving device, another lift magazine disposed out of alinement with said row of magazines, and means for producing a lift from said last magazine and delivering it in dry condition into said receiving device. 75
67. A heel building machine having, in combination, a plurality of lift magazines, a pasting device, a receiving device, means for producing a series of lifts from the magazines, means for advancing said series of lifts in succession past the pasting device and delivering them in a pile into the receiving device, a magazine for containing end lifts and means for producing a lift from said last magazine and delivering it in dry condition into the receiving device prior to the delivery of the pasted lifts. 80
68. A heel building machine having, in combination, a plurality of lift magazines, a pasting device, a receiving device, means for producing a series of lifts from the magazines, means for advancing said series of lifts in rapid succession past the pasting device and delivering them in a pile in the receiving device, a magazine for containing end lifts and means for producing a lift from said last magazine and delivering it into said receiving device in a path different 85 from that traversed by the pasted lifts whereby the end lift is maintained in dry condition. 90
69. A heel building machine having, in combination, a pasting device, a conveyer for producing a lift in position adjacent said pasting device, and means for producing a row of lifts and serially advancing them over the pasting device and depositing them in a pile upon the lift produced by said conveyer. 95
70. A heel building machine having, in combination, a supporting frame, a lift magazine associated therewith, a movable conveyer carried by said frame for producing a lift from said magazine and advancing it into a predetermined position, a pasting device adjacent said predetermined position, a row of lift magazines, and means for producing therefrom a series of lifts in 100
- 105
- 110
- 115
- 120
- 125
- 130

dispersed relation, advancing them serially over said pasting device and depositing them in a pile upon the lift produced by said conveyer.

5 71. A heel building machine having, in combination, a row of lift magazines, means for producing a series of lifts therefrom and positioning them in a row in dispersed relation, a pasting device, an auxiliary magazine disposed out of alinement with said row of magazines and on the opposite side of said pasting device, a conveyer for producing a lift from said auxiliary magazine and advancing it into alinement with said row of lifts, and means for serially advancing said row of lifts over said pasting device and depositing them in a pile upon the lift produced by said conveyer.

20 72. A heel building machine having, in combination, a movable carrier for supporting a row of lifts in substantially the same plane, a receiving device disposed below the plane of the carrier, and means including means for actuating the carrier for feeding the lifts and depositing them in the form of a heel pile upon said receiving device.

25 73. A heel building machine having, in combination, a movable carrier for supporting a row of lifts in substantially the same plane, a receiving device disposed below the plane of the carrier, and means for actuating the carrier to feed the lifts and for depositing them in succession in said receiving device in the form of a heel pile.

30 74. A heel building machine having, in combination, a conveyer, means for producing a series of lifts and depositing them in a row upon the conveyer, a receiving device below the plane of said conveyer, and means including means for actuating said conveyer for feeding said row of lifts serially and concurrently and depositing them successively upon the receiving device in the form of a heel pile.

35 75. A heel building machine having, in combination, a row of lift magazines independently adjustable longitudinally of the machine, an auxiliary wedge lift magazine disposed behind said row of magazines and also longitudinally adjustable, and means for producing lifts from the respective magazines and positioning them in a row.

40 76. A heel building machine having, in combination, a row of lift magazines independently adjustable longitudinally of the machine, a similarly adjustable rotatable magazine disposed behind said row and adapted to contain wedge lifts stacked in alternate relation, means longitudinally adjustable with said auxiliary wedge lift magazine for producing a lift therefrom, and a longitudinally disposed pusher beam for advancing the lift so produced and also producing a series of lifts from said row

of magazines and depositing all of the lifts in alinement.

45 77. A heel building machine having, in combination, a row of lift magazines, an auxiliary magazine disposed out of alinement with said row of magazines, and periodically acting means for producing a lift from each of said magazines and positioning them in a row.

50 78. A heel building machine having, in combination, a plurality of non-alined lift magazines, and means for producing successive series of lifts therefrom and positioning each series in an alined row.

55 79. A heel building machine having, in combination, a plurality of non-alined lift magazines, and means for producing a series of lifts therefrom and positioning them in an alined row, and means for serially feeding said row of lifts so produced and assembling them in a pile.

85 80. A heel building machine having, in combination, a row of lift magazines, a lift magazine disposed out of alinement with said row of magazines, means for producing a lift from the last named magazine, and means for producing a row of lifts from the first magazine and at the same time advancing the lift already produced and effecting its alinement with said row of lifts.

85 81. A heel building machine having, in combination, a row of lift magazines, an auxiliary lift magazine disposed behind said row, means for producing a lift from the auxiliary magazine and positioning it behind said row of magazines, and means for producing a series of lifts from said row of magazines and depositing them in a row and at the same time advancing the lift previously produced and depositing it in alinement with said row of lifts.

100 82. A heel building machine having, in combination, a row of lift magazines, a pusher member for producing a series of lifts therefrom and depositing them in a row in front of the magazines, an auxiliary magazine disposed behind said pusher member, and means for producing a lift from said magazine and positioning it in front of said pusher member prior to the operation thereof, whereby the lift produced from the auxiliary magazine is advanced and positioned in alinement with the lifts produced from the other magazines.

110 83. A heel building machine having, in combination, an intermittently rotatable magazine adapted to contain wedge lifts stacked in alternate relation, means acting during each period of rest of the magazine for producing a lift therefrom, and guiding means for holding down the lift as it is produced.

115 84. A heel building machine having, in combination, a magazine adapted to con-

tain wedge lifts arranged in a stack in alternate relation, means for intermittently oscillating the magazine through a half turn, and a pusher for removing the lowermost lift in the magazine at each period of rest thereof.

85. A heel building machine having, in combination, a magazine adapted to contain wedge lifts arranged in a stack in alternate relation, a depending stem on the magazine, a sleeve below the magazine in which the stem is housed, a shaft within the sleeve, a tongue and groove slip-joint connection between the stem and shaft, means for rotating the shaft in a manner to intermittently rotate the magazine through half a turn, and means for removing a lift from the magazine at each period of rest thereof.

86. A heel building machine having, in combination, a magazine for containing a stack of wedge lifts disposed in alternate relation, mechanism for intermittently rotating the magazine through a half turn, an adjustable carrier for said rotating mechanism and the magazine, and means for supporting said carrier, said carrier with its associated rotating mechanism and magazine being slidable along said supporting means to permit adjustment in position of the magazine.

87. A heel building machine having, in combination, a magazine for containing a stack of wedge lifts arranged in alternate relation, mechanism for rotating the magazine intermittently through half turns, a pusher for removing the lowermost lift in the magazine at each period of rest, means for supporting the magazine, the rotating mechanism and the pusher, and means for supplying power to actuate the rotating mechanism and the pusher, said magazine, rotating mechanism and pusher being slidable along the supporting means to permit adjustment of position of said magazine.

88. A heel building machine having, in combination, a slidable carriage, means for supporting the carriage, a magazine, mechanism for intermittently rotating the magazine and a pusher adapted to be projected through the lower end of the machine mounted on said carriage, and means for actuating said rotating mechanism and said pusher, the carriage being slidable as a unit upon the supporting means to permit adjustment of position of the elements carried thereby.

89. A heel building machine having, in combination, a row of lift magazines, a reciprocating beam for producing a series of lifts from said magazines, an auxiliary magazine disposed behind said beam and adapted to contain wedge lifts stacked in alternate relation, means for producing a lift from said auxiliary lift magazine and

positioning it in front of said beam, and means for rotating the auxiliary magazine a half turn and concurrently actuating said beam.

90. A heel building machine having, in combination, a row of lift magazines, a reciprocating beam for producing a series of lifts therefrom and depositing them in a row, a plurality of auxiliary magazines disposed behind said beam and adapted to contain wedge lifts stacked in alternate relation, a plurality of pushers for producing wedge lifts from said auxiliary magazines and positioning them in front of said beam, means for intermittently rotating said auxiliary magazines through half turns, and means connected with the rotating means of one of said auxiliary magazines for effecting the reciprocations of said beam.

91. A heel building machine having, in combination, a row of lift magazines, means for producing a series of lifts from said magazines, an auxiliary magazine disposed out of alignment with said row of magazines and adopted to contain wedge lifts stacked in alternate relation, means for producing a lift from said auxiliary magazine, means for rotating said magazine through a half turn after the production of each lift, and means for actuating said rotating means and both of said producing means in timed cooperation.

92. A heel building machine having, in combination, a continuously operated conveyor, a series of lift magazines, means for producing successive series of lifts from the magazines and depositing them upon said conveyor, lift alining and pressing devices, and inter-connected mechanism between the actuators for said devices and lift producing means whereby the producing means is operated concurrently with the alining and pressing of the previous series of lifts delivered to said devices.

93. A heel building machine having, in combination, a yieldingly supported receiving device, and means for feeding a succession of lifts into the device in superposed relation and for progressively lowering said device as each lift is fed into position.

94. A heel building machine having, in combination, means for feeding a succession of lifts, and a receiving device yieldingly supported beneath a portion of said feeding means and into which the lifts are deposited in superposed relation, said receiving device being progressively depressed as each successive lift is fed into said device beneath said portion of said feeding means.

95. A heel building machine having, in combination, a supporting member, a receiving device yieldingly supported adjacent to and slightly below said member, and a plurality of feed wheels for feeding a series of lifts across said supporting member and

into said receiving device, one of said feed wheels being disposed above said receiving member and serving in conjunction with each of the lifts as it is delivered into said receiving device to force the receiving device downwardly in steps.

96. A heel building machine having, in combination, a supporting member, a movable receiving device disposed adjacent to and slightly below said supporting member, and feeding means for advancing a plurality of lifts serially across said supporting member and in superposed relation into said receiving device, said feeding means comprising a plurality of continuously operated and independently yielding feed wheels, and a continuously operated and vertically fixed feed wheel disposed over said receiving device and between which and the receiving device the lifts are successively fed.

97. A heel building machine having, in combination, a paste roll, a receiving device disposed beyond said roll, and a plurality of feed wheels disposed above the paste roll and the receiving device for serially advancing a sufficient number of lifts to form a heel over the paste roll and depositing them in superposed relation into said receiving device, said device being progressively forced downwardly by the delivery of the successive lifts thereto.

98. A heel building machine having, in combination, a receiving device, and lift assembling means for delivering a series of lifts in superposed relation into said receiving device, a portion of said lift assembling means being located permanently immediately above said receiving device.

99. A heel building machine having, in combination, a receiving device, a pasting device, and means permanently located over said receiving device and said pasting device for feeding a series of lifts over said pasting device and depositing them in a pile in said receiving device.

100. A heel building machine having, in combination, means for producing a row of lifts, means acting in the direction of the row for serially feeding the lifts, a conveyer disposed transversely of said feeding means upon which the lifts are delivered in superposed relation, and means for depressing said conveyer progressively as the successive heels are assembled, said conveyer being pivotally supported at one end and yieldingly held in position to receive the lifts and adapted to be progressively swung about its pivot as the successive lifts are assembled.

101. A heel building machine having, in combination, means for producing a row of lifts, means acting in the direction of the row for serially feeding the lifts, a conveyer disposed transversely of said feeding means upon which the lifts are delivered in superposed relation, pivotally mounted

means for supporting said conveyer, a guide plate secured to said supporting means and against which the lifts are assembled, and means acting upon said supporting means to yieldingly hold the conveyer in position to receive the assembled lifts.

102. A heel building machine having, in combination, means for producing a series of lifts and feeding them serially to an assembling station, and means for advancing the assembled lifts from said station to a position to be removed by the operator.

103. A heel building machine having, in combination, a receiving device, means for producing a series of lifts, feeding them serially and depositing them in a pile upon said receiving device, and means for actuating said receiving device to advance the pile to a position to be removed.

104. A heel building machine having, in combination, an intermittently movable conveyer, means for feeding a row of lifts in succession and depositing them in a pile upon said conveyer, and means for actuating said conveyer to advance the pile to a position to be removed.

105. A heel building machine having, in combination, a plurality of lift magazines, means for producing a series of lifts therefrom, a pasting device, a conveyer disposed adjacent said pasting device, means for feeding the series of lifts in succession past said pasting device and depositing them in a pile upon said conveyer, and means for causing said conveyer to advance the assembled pile to a position to be removed.

106. A heel building machine having, in combination, a receiving device, means for producing a series of lifts to form a heel and delivering them successively in a pile into said receiving device, and means for removing said pile and imparting to it a partial rotation.

107. A heel building machine having, in combination, a receiving device, means for producing a series of lifts to form a heel and delivering them successively in a pile into said receiving device with their breast edges in substantial alinement, and means for removing the pile in the direction of the breast edges and for rotating the pile through substantially 90°.

108. A heel building machine having, in combination, a row of lift magazines, means for producing a series of lifts therefrom and depositing them in dispersed relation, means for serially feeding the lifts so produced, a transversely disposed conveyer upon which the lifts are deposited in a pile with their breast edges extending in the general direction of the conveyer, means for actuating the conveyer to advance the pile, and means for partially rotating the pile to position the breast edges of the component lifts across the conveyer.

109. A heel building machine having, in combination, a row of lift magazines, means for producing a series of lifts therefrom and depositing them in dispersed relation, 5 means for serially feeding the lifts so produced, a transversely disposed conveyer upon which the lifts are deposited in a pile with their breast edges extending in the general direction of the conveyer, means for 10 actuating the conveyer to advance the pile, and means for removing the pile from said conveyer and effecting its partial rotation.

110. A heel building machine having, in combination, an intermittently movable conveyer, 15 means for producing a series of lifts sufficient to form a heel and delivering them successively in a pile upon said conveyer, and means dependent upon the operation of said conveyer for removing the pile 20 from said conveyer and imparting a partial rotation thereto.

111. The combination with a lift assembling mechanism and a lift alining mechanism into which the assembled lifts are 25 manually transferred from said assembling mechanism, of means dependent upon the operation of said alining mechanism for controlling the operation of said assembling mechanism.

30 112. The combination with a lift assembling mechanism and a lift alining mechanism into which the assembled lifts are transferred from said assembling mechanism, of means dependent upon the operation of said alining mechanism for controlling the operation of said assembling mechanism, and means for interrupting said controlling means and permitting said assembling mechanism to be independently controlled.

45 113. The combination with a lift assembling mechanism for producing and assembling a series of lifts in a pile and a lift alining mechanism into which the assembled pile is transferred, of means for independently controlling the operation of said lift assembling mechanism and said lift alining mechanism, and interconnecting means for causing the controlling means of 50 said lift alining mechanism to actuate the controlling means of said lift assembling mechanism.

55 114. The combination with a lift assembling mechanism for assembling a series of lifts in a pile, and a lift alining mechanism into which the assembled lifts are transferred, of means for independently controlling said mechanisms, and means for controlling said mechanisms as a unit.

60 115. The combination with a lift assembling mechanism comprising means for producing a series of lifts sufficient to form a heel and continuously operated means for assembling said lifts in a pile, and a lift 65 alining, pressing and nailing mechanism

into which the assembled lifts are transferred, of means dependent upon the operation of said second mechanism for controlling the operation of said lift producing means of the first mechanism.

70 116. A heel building machine having, in combination, a receiving device, a pasting device, means for producing a series of lifts, means for advancing said lifts serially over said pasting device and assembling them in 75 a pile in said receiving device, a form into which the assembled pile of lifts is transferred, means for actuating the form to aline and subject the lifts to pressure, and means dependent upon the operation of the 80 form for controlling the production of the lifts.

85 117. The combination with a heel lift assembling mechanism comprising a receiving device and means for producing a series of lifts and assembling them in a pile in said receiving device, of a lift alining and pressing mechanism, comprising a form for receiving the assembled lifts from said receiving device and means for actuating 90 the form to aline and press said lifts, and means controlled by the operation of the lift alining and pressing mechanism for governing the operation of said lift assembling mechanism.

95 118. The combination with a heel lift assembling mechanism comprising a receiving device, means for producing a series of lifts sufficient to form a heel and means for assembling said lifts in a pile in said receiving device, of a lift alining and pressing mechanism comprising a form into which the lifts assembled in the receiving device are transferred and means for actuating the form to aline and press the lifts, and means dependent upon the operation of said lift alining and pressing mechanism for controlling the production of lifts in said assembling mechanism.

100 119. The combination with a lift assembling mechanism comprising means for producing a series of lifts sufficient to form a heel, a receiving device and means for assembling the lifts so produced in a pile in said receiving device, of a lift alining, pressing and nailing mechanism, into which the assembled lifts are transferred from said receiving device and comprising means for alining the lifts, means for applying pressure thereto, means for nailing together the alined and pressed lifts, and means dependent upon the operation of said alining means for controlling the operation of said pressing means, said nailing means and said lift assembling mechanism.

115 120. The combination with a lift assembling mechanism comprising means for producing a series of lifts sufficient to form a heel, a receiving device and means for assembling the lifts so produced in a pile in said 120

- receiving device, of a lift alining and nailing mechanism into which the assembled lifts are transferred from said receiving device and comprising means for alining said lifts, 5 means for nailing together said lifts, and means dependent upon the operation of said alining means for controlling the operation of said nailing means and the production of lifts in said assembling mechanism.
- 10 121. A multiple lift magazine for heel building machines having, in combination, a plurality of channel-shaped members, a pair of supporting tracks, and means for securing said members to said tracks, in parallel relation, by clamping means directly engaging said tracks and an end wall of each member.
- 15 122. A multiple lift magazine for heel building machines having, in combination, a plurality of vertically disposed channel-shaped members arranged in spaced parallel relation, each member having its channel facing the same way for receiving the breast edges of a pile of heel lifts stacked between each two members, a pair of horizontal guide tracks, and means for adjustably securing said members to said tracks.
- 20 123. A heel building machine having, in combination, means for producing a series of lifts and depositing them all in the same plane, a receiving device, and a single means for supporting and delivering the lifts
- 25 serially to and stacking them in said device.
124. A heel building machine having, in combination, means for producing a series of lifts in a row, a common means engaging, supporting and advancing simultaneously all the lifts of the series, and mechanism for actuating said means in a manner to advance the entire row beyond the producing means 35 before another row is produced.
125. A heel building machine having, in combination, means for producing successive series of lifts in a row, and means operating automatically and simultaneously on all the 40 lifts of a series and in the line of direction of the row to remove the row from the producing means before the succeeding series is produced.
126. A heel building machine having, in combination, means for producing a row of lifts, a device at the end of the row in which the lifts are assembled, and means for feeding the lifts serially into said device and removing the heel thus formed from the position where the lifts were assembled.
127. A heel building machine having, in combination, means for producing a series of lifts in a row, and means for feeding them serially to an assembling station and for advancing the assembled lifts from said station to a position for transferral to another machine for a succeeding operation thereon.
